SHIP AND HANDLING MEANS FOR UNDER-WATER MINING EQUIPMENT

Joseph D. Deal, Jr., Nicholas E. Oresko, and John L. Stevens, Jr., Newport News, John E. Flipse, Gloucester, and Robert M. Donaldson, Hampton, Va., assignors to Newport News Shipbuilding and Dry Dock Company, Newport News, Va., a corporation of Virginia
Original application Dec. 24, 1963, Ser. No. 332,999.
Divided and this application Feb. 23, 1965, Ser. No. 434,361

26 Claims. (Cl. 114—5)

ABSTRACT OF THE DISCLOSURE

A ship carrying all of the necessary components for carrying out an underwater mining operation is provided with a central well formed therein opening upwardly and downwardly of the ship. The deck of the ship adjacent the well portion includes guide track means thereon, and a movable support means including a body means is provided, flanged wheels being provided on the body means and running along said track means to guide movement of the movable support means along the deck and over said well portion. The body means includes a substantially V-shaped cutout portion at the forward part thereof to receive a portion of the underwater mining equipment. A central hole is provided through the body means. Clamping means is mounted in overlying relationship to such hole, the clamping means including a pair of clamping members including upper engaging portions adapted to engage and support parts of underwater mining equipment and being substantially semi-circular portions.

Guide means for guiding movement of the clamping members includes a pair of rollers at opposite sides of each of the clamping members, guide rails being provided on the body means and engaging each of these rollers to guide movement of the respective clamping members. Detent locking means for locking the rollers in operative position includes a movable support portion on which each roller is adapted to rest, each movable support portion being normally spring-urged upwardly to be flush with the upper surface of the body means. The spring means is of such a strength as to normally support the weight of the clamping members. When the clamping members are under load when supporting a part of the associated underwater mining equipment, the movable support portions will be moved downwardly so that the rollers will be prevented from rolling back toward inoperative position and will be maintained in clamping position until the load is removed.

Additional guide means for the clamping members includes a pair of guide rods, each guide rod being connected with a clamping member and being slidably supported within holes provided in the body means of the movable support means to guide movement of the clamping members.

A hydraulic ram is operatively connected with each of the clamping members to provide power-operated means for the clamping members. Power drive means mounted on the body means is operatively connected with drive sprockets at the outer side edges of the body means. These drive sprockets are adapted to engage lengths of roller chain secured to the upper surface of the deck means so that intercooperation between the sprockets and the roller chain provide a means for positively driving the movable support means fore and aft of the ship.

Wedge locking means for locking the movable support means in a particular position includes a pair of wedge bearing portions at each side of the body means, each of these wedge bearing portions being of channel-shaped cross sectional configuration and sloping downwardly from

the outer side of the movable support means toward the inner portion thereof. A wedge member cooperates with each of these wedge bearing portions, the wedge members each including an upwardly facing surface which slopes downwardly and inwardly toward the inner portion of the associated support means so as to fit snugly against the downwardly facing surface of the wedge bearing portions. The wedge members include an enlarged body portion which is supported for movement along the deck means of roller members rotatably supported at spaced side portions thereof, these rollers being adapted to roll along inclined portions supported by the deck. A pair of spaced upwardly extending guide members are provided on the deck in association with each of the wedge members to guide movement thereof inwardly and outwardly with respect to the movable support means. A pivotally mounted locking lever is provided and has a portion thereon adapted to cooperate with a portion on an associated wedge member for holding the wedge member in operative locking position. Lugs supported on the deck have holes formed therethrough, and the locking lever has a hole adapted to be aligned with said last-mentioned hole so that a locking pin can be inserted through the aligned holes for holding the locking lever in its locking position.

Elevator means is mounted for vertical movement within the well portion of the ship and above the well portion of the ship. The elevator means includes a body means comprising an open framework having a central opening formed therethrough. Guide means for guiding vertical movement of the elevator includes vertically extending guide portions supported by the ship adjacent the well portion, cooperating roller means being supported on the elevator body means. Roller means are provided at opposite sides of the elevator body means, the roller means including rollers mounted for rotation about axes which are substantially perpendicular to the adjacent rollers at each side of the body means.

Means is provided adjacent the central portion of the body means for attaching gimbal means to the elevator means. Clamping means includes a pair of clamping portions movably supported with respect to the elevator means and movable over the central opening provided through the elevator body means. Each of the clamping portions includes a support portion on the upper part thereof for engaging underwater mining equipment. Each of the clamping members is supported by a plurality of rotatably mounted wheel members which are adapted to roll along guide rails supported on the upper surface of the elevator body means, the wheels being provided with flanges for guiding and retaining the wheels on the guide rails. Power-operated hydraulic ram means is connected with each of the clamping portions for moving the clamping portions toward and away from one another.

The elevator operating mechanism for lifting and lowering the elevator body means includes a plurality of sheaves having cables reeved thereover and connected with the elevator body means. Certain ones of the sheaves are movable relative to one another, ball bearing screw members being provided and having pairs of sheaves interconnected therewith so that rotation of the screw members in one direction causes the sheaves to move away from one another, and rotation in the opposite direction causes the sheaves to move toward one another. Vertical movement of the movable sheave means is guided by a plurality of guide rails which cooperate with lug portions extending from the movable sheaves.

Girders are secured to the side of the well portion adjacent the bottom thereof and extend inwardly to engage the elevator body means and limit the downward movement of the elevator means within the well portion. A plurality of spaced lock members are secured to portions of the ship in fixed relation thereto, portions of the elevator

means being adapted to fit between these lock members, lock pins extending through suitable openings provided in the lock members and said portions of the elevator means so as to positively lock the elevator at the level of the lock members.

The gimbal means includes a pair of substantially oppositely extending radially outwardly directed bearing portions which are journaled for rotation within gimbal support means secured to the gimbal attaching members of the elevator body means. These outwardly directed bearing portions extend from upstanding portions of a first annular portion of the gimbal means so that this first annular portion is mounted for rotation about a first pivotal axis. Also supported on this first annular portion and extending upwardly therefrom are journal portions which serve to rotatably support laterally extending portions of a second annular portion for rotation about a second pivotal axis which extends in a direction substantially perpendicular to said first pivotal axis. A tubular portion is fixed to the second annular portion and has a flange at the lower end thereof with spaced holes formed therein to serve as attaching means to secure the gimbal means to a portion of the underwater mining equipment.

The present application is a division of copending U.S. patent application Ser. No. 332,999, filed Dec. 24, 1963.

The present invention relates to new and novel ship and handling means for underwater mining equipment, and more particularly to mining operations which are carried out at great depths beneath the surface of the sea.

The present invention is directed to the underwater mining of solid substances disposed at the bottom of the sea such as manganese nodules which are resting on the sea bottom and which are found in quantities sufficient for commercial mining at depths ranging generally from 400 feet to 12,000 feet or more beneath the surface of the sea.

The apparatus employed for mining such substances according to the present invention includes a novel ship structure adapted to move through the water over a particular mining area of the sea bottom, a collecting means being provided which moves along the sea bottom itself to collect the solid substances, and a conduit means is provided for transporting the collected solid bodies from the collecting means up to the ship.

The conduit means of the invention is preferably formed of a plurality of individual conduit sections which may be readily assembled and disassembled with respect to one another, and suitable means is provided for stowing and handling these individual conduit sections.

The ship structure is also provided with means for stowing the collecting means and for moving it into and out of its operative relationship with respect to a central well portion provided in the ship through which the underwater mining equipment is lifted and lowered.

The present invention contemplates a completely self-contained ship which is adapted to carry out the underwater mining operations far out at sea, the ship being designed to operate for extended periods of time with all of the equipment required for the underwater mining operation being carried by the ship and stowed on board.

The ship is provided with a novel well portion located at a central part of the ship such that when the ship is in operative mining position, the well portion opens downwardly into the sea and facilitates handling of the mining equipment which depends through this well portion from the ship downwardly to the sea bottom. This enables the large heavy components of the underwater mining equipment to be successfully lowered into position and raised from operative mining position, the well portion being so positioned as to facilitate handling of the ship and positioning of the ship properly for lowering operations.

Since all of the underwater mining equipment is adapted

to be carried to the mining site by the ship, the ship must include means for stowing all of the equipment on board and for handling the equipment to move it from its stowed position into operative mining position and to return it to its stowed position when required.

The underwater mining equipment when supported in operative mining position is suspended downwardly through the well portion formed in the ship, and since the collecting means is travelling along the bottom of the sea while the ship is moving to a certain degree on the surface of the sea with respect to the underwater components, it is necessary to permit a certain amount of relative movement between the conduit means and the ship. Accordingly, means is provided for supporting the conduit means from the ship so that such relative movement may occur.

The mining ship of the present invention includes a unique stowage means for stowing the individual sections of the conduit means in as compact a space as possible, the individual sections being maintained in proper stowed position by suitable guide portions provided within the stowage area which also ensure that the conduit sections are properly guided when being removed from the stowage area or returned thereto.

Means is also provided within the stowage area on the ship in the form of a maneuverable vehicle which permits a single operator to move about within the stowage area and to effectively lift and lower the large conduit sections and move them into the desired position.

Suitable handling means is provided on the ship to enable the handling of the underwater mining components. An overhead bridge crane means arranged for bridge travel in a fore and aft direction and trolley travel athwartships is provided for lifting and lowering the components as required.

In addition, a movable support means is mounted for movement in a fore and aft direction along the deck of the ship, this support means including its own driving means and power operated clamping means which is adapted to engage and support certain of the underwater mining components. Means is also provided for locking the movable support means against movement relative to the deck and further for locking the clamping means in operative position when under load.

Elevator means is provided which is movable into the well portion and thereabove for maneuvering various components of the underwater mining apparatus into the desired position. This elevator means also includes clamping means for clamping and holding portions of the underwater mining equipment. Means is provided for locking this elevator means in several different operative positions as the case may be, and gimbal means is provided for permitting the necessary degree of relative movement between the conduit means and the ship during the mining operation, this gimbal means being operatively supported in a central part of the elevator means.

In addition to the elevator means which is adapted to clamp and hold certain components within the well portion, an auxiliary support means is also provided which is selectively movable into operative position within the well portion for supporting certain components therewithin.

An object of the present invention is to provide a mining ship including means which permits ready access to the sea for lowering large heavy components of the mining equipment into the sea and for lifting such equipment out of the sea, and which is so positioned as to facilitate handling of the equipment on the ship and positioning of the equipment properly for lowering operations.

Another object of the invention is to provide a unique ship for use in underwater mining operations which is a self-contained unit and which includes means for storing all the equipment on board the ship and for handling

the equipment as required to move it into or out of operative mining position.

A further object of the invention is to provide a ship for use in underwater mining operations including means for supporting conduit means utilized in the underwater mining operation in operative mining position and permitting a certain degree of necessary relative movement between the conduit means and the ship.

A further object of the present invention is to provide a ship for use in underwater mining operations including stowage means for stowing individual conduit sections in as compact a space as possible.

Another object is to provide stowage means which effectively holds the individual conduit sections in proper stowed position and which also provides means for properly guiding the individual sections out of the stowage area when the sections are being lifted therefrom.

A further object of the invention is the provision of handling means which allows a single operator to effectively move and position large conduit sections within the stowage area.

A still further object of the present invention is to provide a movable support means which is adapted to support components of the underwater mining equipment and to move relative to the supporting deck surface for transferring components from one position to another.

Another object is the provision of a movable support means which comprises a self-contained unit including its own driving means and power operated clamping means.

A further object of the invention is to provide a movable support means adapted to move relative to a supporting deck surface and including means for holding the movable platform means in fixed position relative to said deck means and also to provide means for holding the movable clamping means of the support means in its operative clamping relationship when the clamping means is under load.

A further object of the present invention is to provide underwater mining equipment including a ship having a well portion therein opening downwardly into the sea and including auxiliary support means having separate support portions which are movable into supporting position to support underwater mining equipment components at the central part of the well, these movable support portions also being movable out of the well portion to provide a substantially unobstructed well area through the ship.

Another object of the invention is the provision of auxiliary support means as defined in the previous object and including an additional means therebelow for engaging and holding certain portions of underwater mining equipment in fixed spaced relation to the walls of the well portion.

A further object of the present invention is to provide apparatus for underwater mining at great depths beneath the surface of the sea including a ship having a well portion therein opening both in an upward and in a downward direction and elevator means associated with said well portion and movable so as to lower components of underwater mining equipment into said well portion and to lift such components out of said well when desired.

Another object is to provide elevator means as aforesaid including means for selectively clamping and holding underwater mining equipment components in position while the elevator means itself is lifted or lowered as the case may be.

A further object of the invention is to provide elevator means as described above which includes gimbal means for supporting mining equipment in operative position and which permits the necessary relative movement between the underwater mining equipment and the ship.

Still another object of the invention is the provision of elevator means movable in an up and down direction

as aforesaid and providing lock and stop means for locking the elevator means in particular operative positions and to limit movement of said elevator means in a downward direction.

5 Other objects and many attendant advantages of the invention will become more apparent when considered in connection with the specification and accompanying drawings wherein:

10 FIG. 1 is a side elevation of a portion of a mining ship according to the present invention with certain parts removed or broken away for the sake of clarity;

15 FIG. 2 is a view taken substantially along line 2—2 of FIG. 1 looking downwardly in the direction of the arrows;

20 FIG. 3 is a sectional view taken substantially along line 3—3 of FIG. 1 looking in the direction of the arrows;

25 FIG. 4 is a sectional view partly broken away through the stowage area for the individual conduit sections according to the present invention;

FIG. 5 is a sectional view taken substantially along line 5—5 of FIG. 4 looking in the direction of the arrows;

FIG. 6 is a sectional view taken substantially along line 5—5 of FIG. 4 looking in the direction of the arrows;

30 FIG. 7 is a top perspective view illustrating the details of construction of the upper support means;

FIG. 8 is a top perspective view of a first form of the lower support means;

FIG. 9 is a top perspective view of a second form of the lower support means;

FIG. 10 is a sectional view taken substantially along line 10—10 of FIG. 5 looking in the direction of the arrows;

35 FIG. 11 is a top perspective view illustrative of the manner in which the conduit sections are secured in place on certain of the upper support means portions;

FIG. 12 is a view looking upwardly within the stowage area illustrating the portable rail section arrangement of the present invention;

40 FIG. 13 is an enlarged sectional view taken substantially along line 13—13 of FIG. 6 looking in the direction of the arrows;

FIG. 14 is a sectional view taken substantially along line 14—14 of FIG. 13 looking in the direction of the arrows;

45 FIG. 15 is a front view partially broken away and partially in section of the handling means employed in the stowage area for lifting, lowering and transporting the individual conduit sections;

FIG. 16 is a view taken substantially along line 16—16 of FIG. 15 and illustrating certain portions in section;

FIG. 17 is a sectional view taken substantially along line 17—17 of FIG. 15 looking in the direction of the arrows;

55 FIG. 18 is a top perspective view partially broken away and with certain parts removed for the sake of clarity illustrating a portion of the stowing area, two different operative positions of the overhead crane mechanism and showing the movable support means in operative position overlying the well portion of the ship.

60 FIG. 19 is a top view of the movable support means according to the present invention;

FIG. 20 is an elevation of the movable support means illustrated in FIG. 19;

65 FIG. 21 is a sectional view taken substantially along line 21—21 of FIG. 20 looking in the direction of the arrows;

FIG. 22 is a sectional view taken substantially along line 22—22 of FIG. 20 looking in the direction of the arrows;

70 FIG. 23 is a sectional view taken substantially along line 23—23 of FIG. 19 looking in the direction of the arrows;

FIG. 24 is a top perspective view partially broken away and with parts removed for the sake of clarity illustrat-

ing the manner in which the auxiliary support means of the present invention is mounted with respect to the well portion of the ship;

FIG. 25 is a sectional view taken substantially along line 25-25 of FIG. 24 looking in the direction of the arrows;

FIG. 26 is a sectional view taken substantially along line 26-26 of FIG. 25 looking in the direction of the arrows;

FIG. 27 is a sectional view taken substantially along line 27-27 of FIG. 25 looking in the direction of the arrows;

FIG. 28 is a top perspective view partly broken away with certain parts removed for the sake of clarity which illustrates the general arrangement and interrelationship of the well portion of the ship, the elevator means, and the means for lifting and lowering the elevator means;

FIG. 29 is a sectional view taken substantially along line 29-29 of FIG. 28 looking in the direction of the arrows;

FIG. 30 is a sectional view taken substantially along line 30-30 of FIG. 29 looking in the direction of the arrows;

FIG. 31 is a view looking downwardly in the direction of the arrows along the line 31-31 of FIG. 30;

FIG. 32 is a sectional view taken substantially along line 32-32 of FIG. 29 looking in the direction of the arrows;

FIG. 33 is a sectional view taken substantially along line 33-33 of FIG. 30 looking in the direction of the arrows;

FIG. 34 is a top view partly broken away of the elevator means itself;

FIG. 35 is a sectional view taken substantially along line 35-35 of FIG. 34 looking in the direction of the arrows;

FIG. 36 is a sectional view taken substantially along line 36-36 of FIG. 35 looking in the direction of the arrows;

FIG. 37 is a sectional view taken substantially along line 37-37 of FIG. 36 looking in the direction of the arrows;

FIG. 38 is a top perspective view illustrating the construction of the gimbal means of the present invention;

FIG. 39 is a top view of the gimbal construction shown in FIG. 38; and

FIG. 40 is a sectional view taken substantially along line 40-40 of FIG. 39 looking in the direction of the arrows.

Referring now to the drawings wherein like reference characters designate corresponding parts throughout the several views, there is shown in FIGS. 1, 2 and 3 an intermediate portion of a mining ship according to the present invention. It will be understood that the structure as illustrated in these figures is spaced a substantial distance both from the bow and stern of the ship and that the well portion therein is disposed substantially symmetrically about the longitudinally extending center line of the ship. As seen in these figures, the well portion 125 extends completely through the ship and opens in an upward direction and also downwardly into the sea. A separator mechanism 130 is provided on the deck of the ship and is adapted to separate out the collected solid bodies or manganese modules while rejecting the sea water and any superfluous material of an undesirable nature. The solid bodies are then discharged from the separator mechanism onto a portion of a longitudinally extending conveyor mechanism 132, and as seen in FIG. 2, a hatch 345 is adapted to receive solid bodies from a conveyor portion 346.

As seen particularly in FIGS. 1 and 3, the elevator machinery area is located just aft of the well portion 125, and a spare motor and pump for use in the pumping means of the underwater mining apparatus are indicated respectively by reference numerals 1240 and 1245, these

spare components being supported on a suitable deck above the elevator machinery space. The pipe stowage area is indicated generally by reference numeral 142.

An overhead travelling crane is indicated generally by reference numeral 364, and as seen particularly in FIG. 3, the overhead crane mechanism includes a transversely extending body portion 365 having wheels or rollers 366 mounted at the opposite sides thereof and which are supported upon rails 368. These rails extend substantially parallel with the center line of the ship and longitudinally thereof, and are supported by portions 370 of the superstructure. The wheels 366 of the crane mechanism preferably have positive engagement with the track portions 368 to prevent fore and aft runaway of the crane mechanism.

A trolley means 372 as seen most clearly in FIG. 18 is mounted for movement athwartship by means of wheels 373 mounted upon suitable transversely extending track portions 374. The trolley wheels also preferably have positive engagement with the associated tracks to prevent athwartship runaway. Suitable conventional means is provided for driving the main crane body portion 365 and the trolley 372 so as to properly operatively position a depending hook mechanism indicated by reference numeral 375. A winch or other suitable lifting and lowering means is indicated by reference numeral 377 and is operatively connected with the hook means and supported by the trolley means whereby the hook means may be operatively positioned in any desired location. The crane cab within which an operator is supported is indicated by reference numeral 378.

Referring now particularly to FIG. 2, the reinforced construction of the upper deck adjacent to the well portion is illustrated. A plate 403 is provided of heavy-duty construction and in a typical example may be a 56.1 lb. plate. A pair of insert plates 405 and 406 are provided, these plates being of a similar weight to plate 403 and being provided at the corner portions of the well portion and having arcuate edge portions adapted to conform to the arcuate corners of the well portion, these arcuate corners being indicated by reference numerals 408 and 409. The adjacent plates as indicated by reference numerals 410 and 411 may be of usual upper deck construction and in a typical example may comprise 38.25 lb. plates.

It is apparent that the ship is provided with a reinforced upper deck adjacent to the lateral portions and corners of the well portion so as to reinforce these portions and to provide adequate rigidity and strength to the ship adjacent the well portion which extends completely through the ship in a vertical direction from the bottom shell to the upper deck.

A plurality of vertically upstanding members 413, 414, 415, 416, and 417 are provided at one side of the well portion and a corresponding plurality of upstanding vertical members 413', 414', 415', 416' and 417' similar to the first mentioned support members are provided at the opposite side of the well portion. It will be understood that these vertically upstanding members are portions of the superstructure which supports the overhead crane structure previously described. A pair of support members 420 and 421 extend upwardly from the outer lateral portions of the ship and slope inwardly to join with the superstructure at a point spaced a considerable distance above the deck to provide lateral stability for the superstructure.

The generally rectangular outline of the well portion 125 is indicated in dotted lines in FIG. 2, but the well portion is not of this configuration completely from the bottom shell to the upper deck, but is only of such generally rectangular configuration from the bottom shell to an intermediate portion of the well portion whereat certain inwardly extending bulkheads are provided as hereinafter described. The upper deck area is provided with recessed portions so as to provide clearance for the

elevator structure and auxiliary support structure hereinafter described, and as seen in FIG. 2 the upper deck is provided with a main generally rectangular recessed portion from which extend a first pair of rectangular recessed portions 423 and 424 at the aft portion of the main recessed portion, a second pair of rectangular recessed portions 426 and 427 extending laterally from an intermediate portion of the main recessed portion, and a third pair of rectangular recessed portions 429 and 430 extending outwardly from opposite sides of the forward portion of the main recessed portion. A recessed portion 432 extends forwardly of the well portion and is of generally rectangular configuration, and a recessed portion 433 of substantially V-shaped configuration extends aft of the well portion and will be more fully discussed hereinafter.

The elevator means is indicated generally by reference numeral 435 and has laterally extending portions thereof which fit within the recessed portions 423, 424, 426, 427, 429 and 430 previously described, the structure of the elevator mechanism being more fully set forth herein-after.

Elevator sheave trunk portions 437 and 438 extend vertically upwardly from plate 405 and a similar plate 405' for receiving and protecting the sheaves and cables employed for lifting and lowering the elevator mechanism as hereinafter set forth. Holes 440 and 441 are provided in plates 405 and 405' respectively for allowing movement of the operating mechanism for the elevator mechanism therethrough.

Various components of the underwater mining equipment are illustrated in their normal stowed position on the upper deck of the ship as seen in FIG. 2, a collecting means 167 being supported on the deck in the position illustrated. The collecting means in this stowed position is disposed in overlying relationship to a first recessed hatch 443 which provides access to the stowage area for the individual sections of the conduit means. This collecting means is also in overlying relationship to an unshipping opening 444 to the elevator machinery room as hereinafter described.

It will be understood that the collecting means 167 as seen in FIG. 2 is disposed flat upon the deck, and an additional or reserve collecting means of substantially identical configuration is indicated at 167', this collecting means being stowed on end or at a substantially right angle position to that of collecting means 167, the reserve collecting means 167' being supported by a suitable support frame 446 which is preferably mounted for pivotal movement about an axis 448 with respect to the deck. With this arrangement, the support frame 446 can be pivoted up into the stowed position as shown, or can be pivoted downwardly so as to place the reserve collecting means 167' in position for lowering it into operative mining position if so required. In addition, a further collecting means (not shown) may be stowed at the opposite side of the collecting means 167 as shown in a manner similar to the reserve collecting means 167'.

As illustrated in FIG. 2, it is assumed that the truss construction adapted to be connected at the lower end of the conduit means to the collecting means is such that the over-all truss means is formed of a plurality of individual truss sections which can be readily interconnected and disconnected as required. In FIG. 2, the first truss section is indicated generally by reference numeral 450, this truss section being pivotally interconnected as indicated at 451 with the collecting means 167. With this arrangement, the first truss section which is connected with the collecting means may remain pivotally interconnected therewith at all times, and the remaining truss sections are stowed in vertically extending positions, these remaining truss sections being indicated by reference numerals 453, the various sections being interconnected with one another and lowered into operative position. It is apparent that the truss sections occupy as little deck space

as possible when stowed in such vertically extending position, and a portion of one of the truss sections may extend over the recessed portion 432 in the deck as illustrated. Portable guard rails 454 and 455 are provided adjacent the well portion and the recessed portion 432 in the main deck to prevent personnel from accidentally falling into these recessed portions.

A pair of longitudinally extending tracks are provided for supporting certain movable equipment hereinafter described, the port track means including sections 458, 458', 458" and 458'', and the second rail means including sections 460, 460', 460" and 460''. It will be noted that the two track means are substantially parallel with one another and that the various sections thereof are interrupted by the recessed portions formed in the main deck, but however, the spacing between the various track sections as occasioned by these recessed portions is such that the movable equipment which is provided with wheels is continuously supported and guided by the tracks, or in other words some of the wheels are maintained in contact with the track sections at all times in order to maintain the proper degree of support and guidance.

A first movable support means or platform dolly 462 is provided, this platform dolly being provided with wheels as hereinafter described which are movable along the tracks on the deck so that the platform dolly can move longitudinally back and forth as hereinafter described. The platform dolly is illustrated as supporting in stowed position thereon a dead weight means 153.

A second movable support means or capsule dolly is indicated generally by reference numeral 464, this dolly being provided with wheels as hereinafter discussed and being movable along the tracks on the deck. This capsule dolly is illustrated as supporting thereon in stowed position the pump capsule 152.

A third support means is indicated generally by reference numeral 466, this support means being movable athwartships and serving to support in the stowed position a buoyancy capsule indicated generally by reference numeral 467. This buoyancy capsule is simply a large water-tight container which is adapted to be attached to the conduit means to provide buoyancy thereto as will be more fully discussed hereinafter.

As seen in FIG. 1, the dead weight means 153 includes a small conduit portion 470 extending upwardly therefrom including an intermediate collar portion 471 for facilitating handling of the dead weight means. An upper flange portion 472 is provided at the top of the conduit portion 470 and includes suitable holes formed therein for bolting this flange to a cooperating flange of a conduit section.

Conduit section stowage means

Referring now particularly to FIGS. 4, 5 and 6, the general arrangement and layout of the stowage area may be most clearly understood. As seen in these figures, the upper deck of the ship is indicated by reference numeral 635 and the access hatch to the stowage area is indicated by reference numeral 443. The stowage area itself is defined by a forward wall portion 637, a pair of side wall portions 638 and 639 and a rear wall portion indicated generally by reference numeral 640. Upper support means is provided for supporting an upper portion of the individual conduit sections, this upper support means including a plurality of spaced portions indicated by reference numerals 642 which extend substantially longitudinally of the ship, and a pair of transversely extending portions 643 are provided for a purpose hereinafter described. It should be understood that only half of the upper support means is seen in FIG. 6, the other half having been broke away to disclose the underlying lower support means.

Referring particularly to FIG. 7, the construction of the upper support portions may be more clearly understood. As seen in FIG. 7, the spaced portions 642 are

provided with a first plurality of substantially arcuate cutout portions 645 which extend downwardly from the upper surfaces of the support portions only a minor portion of the thickness of the support portions.

Each of the spaced support portions is also provided with a plurality of substantially arcuate cutout portions 646 which extend downwardly from the upper surface of the support portions a substantially greater distance than the cutout portions 645. It will be noted that adjacent spaced portions thereby include pairs of opposed cutout portions, adjacent pairs of such cutout portions extending downwardly different distances from the upper surfaces of the support portions.

These pairs of opposed cutout portions are adapted to receive the upper flange of individual conduit sections as indicated in phantom line in FIG. 7. By providing adjacent pairs of recesses of different vertical depth from the top of the support portions, it is possible to store the conduit sections in staggered relationship with the flanges of adjacent ones of the conduit sections disposed in overlapping relationship with one another as will be most clearly understood from inspection of FIG. 4.

This permits the conduit sections to be stored in rows in the spaces defined between adjacent spaced portions of the upper support means, with the conduit sections disposed in as compact a relationship as possible thereby minimizing the amount of space required to stow a desired number of conduit sections.

The spaces adapted to receive the rows of conduit sections are indicated by reference numerals 648 in the upper portion of FIG. 6, it being understood that the support means is empty as shown.

Referring to FIG. 7, movable support means 650 are pivoted at one end thereof as indicated at 651 to the support means and are adapted to swing across the open end of the spaces defined between the portions of the upper support means into a position as shown in the upper part of FIG. 7 wherein the movable support means is blocking off the space. On the other hand, the movable support means may be swung into the position at the lower part of FIG. 7, so as to open the space. These movable support means are adapted to close off certain of the spaces and to retain the conduit sections in the rows which they normally occupy when in stored relationship. When it is desired to remove the conduit sections from any particular row, the movable support means 650 is swung into a position so as to open the space as illustrated in the lower portion of FIG. 7. It will be noted that each of the movable support means is provided with a cutout portion 651 in the lower edge thereof which is adapted to fit over a bolt or the like 652 extending outwardly from the outer end of the associated portion of the upper support means.

Referring now to the lower portion of FIG. 6, a first plurality of lower support member means is indicated by reference numerals 655 and a second plurality of lower support means is indicated by reference numeral 656. It will be understood that not all of the lower support means have been illustrated in FIG. 6, and that there is a lower support means to correspond with each supported conduit section, it being noted that there is a lower support means directly beneath each opposed pair of cutout portions in the upper support means, there also being provided three lower support means to correspond for each of the three cutout portions 657 formed in the transversely extending upper support portions 643.

Referring to FIG. 8, the construction of the first support means 655 is illustrated, and it will be noted that this simply comprises a substantially disc shaped member which extends upwardly a small distance above the supporting deck surface 659, and which includes an upper tapered edge 660 to facilitate entry of this portion into the lower open end of a conduit section.

Referring now to FIG. 9, the construction of the support means 656 is illustrated, and it will be noted that

this particular form of support means includes a substantially disc like portion 662 supported on a plate 663 which in turn is supported by three transversely extending rib portions 664 which in turn are supported upon the underlying deck support surface 659. An upper tapered edge 665 is provided to facilitate entry of this portion into a conduit section.

It is apparent that the support means 656 extend upwardly from the supporting deck surface 659 a distance which is substantially greater than that which the support means 655 extend upwardly therefrom. The support means 655 which is of lesser height is disposed beneath the opposed cutout portions 646, whereas the support means 656 is disposed below the cutout portions 645 in the upper support means. With this arrangement, the upper and lower support means are adapted to engage and support the upper and lower portions of associated conduit sections as will be well understood.

Referring now particularly to FIG. 11, the manner in which the conduit means are supported on the upper support portions 643 is illustrated. As seen in this figure, one of the three conduit sections supported by each of the support portions 643 is illustrated, the conduit section being indicated by reference numeral 590 and including an upper flange 595. In order to retain this upper flange in its operative position within the arcuate cutout portion formed in support portion 643, a strap means 667 is disposed around the outer surface of the conduit section 590, opposite ends of the strap means being held in operative position by suitable means such as bolts 668, one of which is visible in FIG. 11. It will be understood that the conduit sections supported by each of the upper support portions 643 are held in normal stowed position by similar means, lower support means 655 being disposed therebeneath for engaging and supporting the lower end portions of these conduit sections.

Referring now particularly to FIGS. 4 and 5, a catwalk means 670 is supported within the stowage area by the wall portions previously described which define the stowage area, this catwalk means being disposed in overlying relationship to the upper support means and also being spaced a substantial distance below the upper deck 635.

As seen particularly in FIG. 5, this catwalk means is composed of a plurality of portions 672 defining spaces 673 therebetween. These spaces are substantially aligned with the central portions of the spaces defined between the upper support means portions previously described such that the spaces 673 defined by the catwalk means are adapted to receive part of the conduit section handling means hereinafter described. The catwalk means of course permits personnel to walk around and to permit an operator to readily gain access to the handling means as hereinafter set forth.

Track means is supported beneath the upper deck 635 for supporting the handling means, this track means consisting of a plurality of main track portions 675 each of which is of a substantially I-beam cross sectional configuration for supporting the handling means. These main track portions are supported substantially over the center lines of the spaces between the upper support means portions previously described such that the handling means is adapted to move over these spaces and to permit engagement of the conduit sections supported within these spaces for lifting and lowering the conduit sections when removing them from stowage or returning them to stowage.

It will be understood that in both FIGS. 5 and 6, the upper and lower portions thereof represent different vertical levels, and that in FIG. 6, the upper support means has been broken away at the lower half of the figure to illustrate the lower support means whereas in FIG. 5, the catwalk means has been broken away in the upper half of the figure to illustrate the track means. In each case it should also be fully understood that the upper and lower

support means as well as the catwalk and the track means is symmetrical on either side of the center line of the ship which is equivalent to a centerline drawn horizontally through these figures.

The track means includes a plurality of turntable track portions 677 one of which is illustrated in detail in FIG. 10. As seen in FIG. 10, each of the turntable track portions includes a substantially disc shaped portion 680 having a shaft means 681 extending upwardly therefrom and supported by suitable bearing means indicated at 682 supported by the upper deck. With this arrangement, the disc like portion 680 is mounted for rotation through an angle of 360°. A track means 684 in the form of a member having a substantially inverted T-shaped cross-sectional configuration is secured to the undersurface of the disc means and is adapted to be swung into position so as to be aligned with one of the main track portions 675 or to be aligned with an adjacent track portion of a turntable track portion as hereinafter described.

As seen particularly in FIGS. 4, 5 and 6, guide means for guiding the vertical movement of the conduit sections out of the stowage means includes guide rail means comprising three spaced guide rails 687, 688 and 689 which extend substantially vertically within the stowage area to a point closely adjacent the access hatch 443. The guide rails 688 and 689 are of substantially H-shaped cross sectional configuration as seen particularly in FIG. 14, while the remaining guide rail portion 687 is of substantially T-shaped configuration. This guide rail 687 is also removable so as to enable access of the handling means hereinafter described to a particular space between the portions of the upper support means as will be hereinafter explained.

A movable guide portion is indicated generally by reference numeral 691, this guide portion having a substantially triangular shaped configuration including the side portions 693, 694, 695 as seen in FIG. 14. A first plurality of guide rollers 697 are rotatably supported by spaced portions of the movable guide portions and are adapted to engage parts of the guide rail 688 to guide vertical movement of the movable guide portion. A similar plurality of rollers 698 are rotatably supported by the movable guide portion and cooperate with guide rail 689 to guide vertical movement. A third plurality of guide rollers 699 are rotatably supported by the movable guide portion and engage parts of the movable guide rail 687 for guiding the movement of movable guide portion 691. It is apparent that the movable guide portion will be accurately guided in its vertical movement by the interengagement of the guide rollers with the guide rails. As seen in FIG. 13, a bumper means 700 is provided on the lower portion of the movable guide portion in order to prevent damage to the undersurface thereof and to cushion the fall of the movable guide portion as hereinafter described.

As seen particularly in FIG. 14, the side portion 693 of the movable guide portion is provided with a pair of spaced bosses 702, side portion 694 of the movable guide portion being provided with a pair of similar bosses 703, and the remaining side portion 695 of the movable guide portion being provided with a pair of spaced bosses 704. Three similar detent members indicated generally by reference numerals 706 are provided, each of these detent members being pivotally supported upon pin means 707, the three pin means being mounted between adjacent pairs of bosses 702, 703 and 704.

The pivotally mounted detent members comprise a means for engaging a lower portion of a conduit section for interconnecting the movable guide portion with a lower portion of the conduit section as hereinafter described. Each of the detent members 706 is constantly urged into the operative position shown in FIGS. 13 and 14 by associated spring members 709 which are wrapped around the pin means upon which the detent members are mounted, the spring means engaging the detent members for

urging them in the desired direction of rotation about the supporting pin means. Suitable means such as a lug 710 as seen in FIG. 13 may be connected with the associated bosses 702, 703 and 704 for engaging the detent members and limiting inward pivotal movement thereof.

As can be seen most clearly in FIG. 13, each of the detent members 706 is provided with an upwardly facing cam surface 712. A lower flange of a conduit section is indicated by the phantom line 600, this conduit section being lowered into position by the handling means hereinafter described. A support means 656' which is substantially identical with the support means 656 previously described in connection with FIG. 9 is fixed to the supporting deck surface and is adapted to guide the lower portion of the conduit section into proper operative position. It will be apparent that as the conduit section is lowered into the operative position shown, the lower flange of the conduit will engage the upwardly facing cam surfaces 712 of each of the detent members and will cam the detent members out of the way so that the conduit section may be lowered into the position shown with the bottom flange of the conduit section supported on the support means 656'. When the conduit section reaches this position, the spring means 709 will cause each of the detent members 25 to pivot back into its operative position shown whereupon the downwardly facing lower surface 714 formed on the upper portion of each of the detent members will be adapted to engage the upper surface of the lower flange on the conduit section. When the detent members are in 30 this position, it is apparent that the movable guide portion will be operatively interconnected with the lower flange of the conduit section.

When the movable guide portion has been operatively connected with the lower flange of the conduit section as 35 discussed above, the conduit section can then be raised in a vertical direction carrying the movable guide portion 691 along therewith. The guide rollers on the movable guide portion will cooperate with the guide rail means previously described so as to accurately guide the conduit 40 section in its upward vertical movement.

Referring now to FIG. 12, three spaced projections 716 are supported from the undersurface of the main deck, these projections being spaced in overlying relationship to the detent members 706 and being adapted to engage surfaces 718 on the detent members. As seen in FIG. 13, each of the last-mentioned surfaces 718 are disposed in a substantially horizontal position when in the operative connected relationship as shown, and accordingly as the movable guide portion is carried upwardly by an associated conduit section, the projections 716 will engage the surfaces 718 on the detent members so as to cause them to pivot out of the operative connected relationship with the lower flange of an associated conduit section whereby the movable guide portion will be released from the associated conduit section. The conduit section may then be 50 raised further above the main deck and maneuvered into the desired position for lowering into mining relationship as hereinafter described.

When the movable guide portion is so released from an 60 associated conduit section, it will drop under the influence of gravity down along the associated guide rail means, and the bumper means 700 at the bottom thereof will cushion the fall of the movable guide portion and prevent damage thereto. The movable guide portion will then be 65 in the position as seen in FIG. 13 adapted to receive the lower flange of another conduit section.

Stowage area handling means

Referring now particularly to FIGS. 15, 16 and 17, the handling means for handling the individual conduit sections to move these sections into and out of the stowage position within the stowage means is illustrated. This handling means includes a body means indicated generally by reference numeral 720, this body means having a 70 channel-like cross sectional configuration as seen in FIG. 75

17 and serving to rotatably support a first pair of upper and lower rollers 722 and 723 at either side thereof at one end of the body means and a second pair of upper and lower rollers 724 and 725 at opposite sides thereof at the other end of the body means. These pairs of rollers are adapted to engage the upper and lower surfaces of the lower flange of a supporting overhead track means as previously described which is of substantially I-beam cross sectional configuration. As seen in FIG. 17, the particular track portion shown includes an upper flange 727, a central web portion 728 and a lower flange 729. It will be apparent that the rollers aforesaid serve to support the body means for movement along the track, and further that the body means will be guided for movement along such track and cannot escape therefrom.

A drive motor 730 is supported by the body means, this drive motor as seen particularly in FIG. 17 including a driving sprocket 732 which is adapted to positively cooperate with a chain belt 733 or the like, which can be suitably secured as by welding to the undersurface of the track means. It is apparent that by controlling the speed and direction of rotation of the drive motor, the speed and direction of movement of the body means can be controlled, a positive driving connection being provided for this purpose.

A plurality of spaced depending arms 736 extend downwardly from the body means, and a substantially cylindrical portion 737 is connected with the lower ends of these arm portions. A substantially annular support 740 is supported by bearing means 741 and 742 for rotation through 360° of movement about the lower part of the cylindrical portion 737, an outwardly projecting portion 745 serving to support this rotatable cylindrical portion. The portion 745 may be formed integral with or separate from the cylindrical portion and is fixed with respect thereto. The support means 740 includes an outwardly and upwardly extending portion 747 upon which an operator's seat 748 is supported, a foot rest 749 also being provided to enable an operator to sit on the seat and to move about the handling means as required to properly direct the handling means. An upwardly extending portion 751 supported by the support means 740 serves to support a control panel 752 including suitable controls for controlling the operation of the handling means.

A bearing means 755 is supported by the body means and serves to rotatably journal a shaft 756 having a pulley 757 connected to the upper end thereof, the lower portion of said shaft having suitable screw thread means 758 formed thereon. The screw thread means is adapted to cooperate with a nut portion 760, rollers or balls 761 being provided for engaging the screw thread means 758 of shaft 756 to provide a so-called ball-screw interconnection.

Nut 760 is fixedly connected to the upper portion of a tubular member 764 which is adapted to move upwardly and downwardly with respect to the body means. A key 765 is provided on the outer surface of the tubular member or movable support means 764 and is adapted to engage a suitable keyway provided in the cylindrical member 737 for preventing relative rotation between the tubular member 764 and the cylindrical member and body means. An operating motor 767 is provided with a pulley 768 and is interconnected by a suitable driving belt or the like 769 for controlling the rotation of shaft 756.

An enlarged portion 772 is provided at the lower end of the tubular member 764, this enlarged portion including a substantially frusto-conically shaped outer cam surface 773. A support member 775 which is of generally disc-like configuration includes a central opening 776 through which the tubular member 764 extends and is movable with respect thereto. A second key means 778 is provided on the outer surface of tubular member 764 and is adapted to engage in a suitable keyway provided in the support member 775 for preventing relative rotation

between the support member and the tubular member.

Movable clamp means includes a plurality of movable clamping members 780 of similar construction which may be four in number, the detail of construction and mode of mounting the individual clamping members being most clearly seen in FIG. 15. As seen in this figure, it will be noted that each of the clamping members includes a lower sloping cam portion 782 which is disposed at an angle so as to be complementary to the outer cam surface 773 provided at the lower end of the tubular member 764. The upper portion of each of the clamping members extends through a suitable radially extending slot means 784 provided in the undersurface of support member 775 whereby each of the clamping members is movable inwardly and outwardly in a radial direction. The upper portion of each of the clamping members may be of substantially T-shaped cross sectional configuration, and the slot means may be of complementary configuration so as to receive the clamping members, to support the clamping members and prevent them from falling downwardly out of the support member, and to additionally guide radial movement thereof as will be well understood.

A resilient compression spring means or the like 785 is provided in engagement with each of the individual clamping members for normally urging the clamping members in a radially inward direction as will be apparent.

A pair of diametrically opposite arm members 787 are provided, each of these arm members being mounted for pivotal movement about pin means 788 supported by the support member 775. The lower ends of each of these arm members are provided with radially inwardly extending substantially cylindrical pin means 790 which are adapted to cooperate with eye-bolts or the like indicated by phantom lines 791 which are connected with the upper flange of an associated conduit section as indicated by phantom line 792.

Upwardly extending support means 795 are provided on support member 775 at diametrically opposite sides 40 of the tubular member 764, these support members supporting solenoid means 796 each of which is adapted when energized to pull the armature means 797 thereof radially inwardly so as to pivot the upper ends of the arm members inwardly and the outer ends thereof outwardly. Compression spring means 798 is operatively connected between each of the support members 795 and the adjacent upper portions of the associated arms so as to normally pivot each of the arms such that the upper portions thereof tend to move radially outwardly and the lower portions thereof tend to move radially inwardly.

Conduit section removal and stowage procedure

All handling operations concerning the conduit sections when removing or stowing them with respect to the stowage area should be carried out with the ship on as near 55 even keel as possible.

The forward six conduit sections disposed in a row extending athwartships are the first and last to be handled in the removal and stowage procedures respectively. Firstly, the procedure to be followed in removing the forward 60 six conduit sections will be described.

An operator mounts the operator's seat of the handling means and maneuvers the handling means apparatus through the intermediary of the controls provided at the operator's seat so as to position the handling means apparatus on one of the turntable track portions over the center line of a first conduit section either to the starboard or port of the access hatch 443 to the stowage means. Short fixed track portions 678 are supported adjacent the inboard turntable track portions as seen in FIG. 5 to permit the handling means to travel from the access hatch 443 to the turntable track portions.

The motor 767 of the handling means is then energized so as to lower the tubular member 764 with respect to 75 the body means through the intermediary of the ball screw

means previously described until the arm members 787 are supported in such a position as to move into operative relationship with eye-bolts or the like secured to the upper flange of the conduit section.

The operator then de-energizes the solenoids 796 and the arms 787 are automatically moved inwardly by means of the spring means 798 and the pin means 790 enter the holes in the eye-bolts and assume the operative lifting position as shown in FIG. 15. The operating motor 767 is again energized except in a reverse direction to that previously described so as to cause tubular member 764 to start to rise. As the tubular member rises, the cam surface 773 formed on the lower enlarged portion thereof interacts with the cam surface on the clamping members 780 which cannot move upwardly due to the interengagement of the pin means with the eye-bolts on the associated conduit section. The aforementioned interengagement of these cam surfaces causes the clamping members to be moved radially outwardly such that the outer surfaces thereof engage the inner surface of the bore within the associated conduit section.

When the clamping members have been so interengaged with the conduit section, further upward movement of the tubular member will cause the conduit section to move upwardly therewith. As soon as the conduit section starts to rise, upward travel of the tubular member 764 is stopped by de-energizing the driving motor 767.

At this point, the strap 667 as seen for example in FIG. 11 is removed from around the conduit section such that the conduit section is then free to move upwardly. The conduit section is then further raised by raising tubular member 764 of the handling means until the lower end portion of the conduit section clears the lower support means upon which it has been resting.

The handling means apparatus is then moved by the operator along the associated turntable track portion and thence onto one of the athwartships track portions 678 to a point adjacent the access hatch 443. Referring to FIG. 12, which is a view looking upwardly at the access hatch, a portable rail section 800 is supported on the undersurface of a member 801 which is adapted to fit within the access hatch and to be supported at such point. As shown, the portable rail section 800 is illustrated as being aligned with a particular main track portion 675'. A first phantom line 803 indicates the manner in which another member similar to the member 801 can be provided with a portable rail section aligned with a main track section 675'. In a similar manner, phantom lines 804 and 805 illustrate arrangements wherein a member similar to member 801 may be provided with rail sections aligned either with the main rail section 675' or with the athwartships sections 678. It will accordingly be understood that in the procedure presently being discussed, a member having a rail section is positioned in the access hatch 443 so that the handling means may be moved into such a position that it is centered over the support means 656' disposed at the bottom central portion of the vertically extending guide means previously described.

After the conduit section has been moved into this position, the conduit section is lowered by lowering tubular member 764 of the handling means until the lower portion of the conduit section is supported on the support means 656' as illustrated in FIG. 13.

As the conduit section moves downwardly, the detent members 706 previously discussed in connection with the guide means will first be cammed out of the way and then will snap into operative position as shown in FIG. 13. After these detent members have engaged the lower flange on the conduit section, the conduit section is strapped in position by providing a strap around the upper portion thereof in a manner similar to that previously discussed in connection with FIG. 11.

With the conduit section strapped in such position, the tubular member 764 is again lowered. As the tubular

member moves downwardly, the cam surface 773 at the lower end thereof will move down thereby permitting the spring means 785 to force the clamping members 780 radially inwardly. The solenoids 796 are then energized to move the arms 787 such that the pins 790 will be moved outwardly out of operative relationship with respect to the eye-bolts secured to the conduit section.

The tubular member 764 is then again raised so as to lift the entire apparatus clear of the conduit section whereupon the handling means may be maneuvered into position for handling another conduit section. It will be understood that the procedure as described above is followed until all of the first six conduit sections extending in a row athwartships in the stowage area have been removed.

The removal of conduit sections from any of the various fore and aft rows involves a procedure similar to that described above except for certain exceptions as described hereinafter. When removing conduit sections from either of the last four port or starboard rows of conduit sections, it is necessary to employ the turntable track portions in order to transfer the handling means from an athwartships position to a fore and aft position. In other words, if the handling means is moving in an athwartships direction, and it is desired to move it onto one of the main track portions extending fore and aft, the handling means is positioned on the turntable track portion and stopped in such position whereupon the disc-like turntable portion thereof is rotated so as to properly align the track portion thereof with the fore and aft track portion, whereupon the handling means can be moved onto such main track portion. It is believed that the manner of operation of the turntable track portions will be apparent from a consideration of FIG. 5 in connection with the above description.

Before the handling means can enter any of the rows of conduit sections, which are provided with the movable supports, it is of course necessary to swing such movable support into the position as shown at the lower part of FIG. 7 in order for the handling means to move into operative position. The movable supports will then of course be replaced when the desired number of conduit sections have been removed.

When removing conduit sections from the center row of conduit sections extending fore and aft within the stowage means, it is necessary to remove the aft guide rail 687 which of course is replaced prior to lifting a conduit section vertically out of the access hatch 443.

It will of course be understood that when removing conduit sections from either the central fore and aft row or from either of the first rows port and starboard of this central row, it is necessary to employ a portable track means as shown in FIG. 12 aligned with the main track means disposed over such row in order that the conduit sections may be moved to the central portion beneath the access hatch.

It should be understood that stowage of the conduit sections within the stowage area involves a procedure which is the reverse of the removal procedure described above.

Referring now to FIG. 18, after the conduit section is positioned beneath the center line of the access hatch 443, a hook 375 is lowered by the bridge crane and engages a cable or the like 811 connected between the eye-bolts at the upper flange of the conduit section. All slack is removed from the cable until the conduit section starts to rise whereupon the strap around the conduit section is removed. The conduit section is then raised through the access hatch by the bridge crane.

When the lower flange of the conduit section nears the main deck level, the detent members 706 of the movable guide portion engage the projections 716 as seen in FIG. 12 thereby releasing the detent members such that the movable guide portion falls back to its initial position.

ready to receive another conduit section from the handling means.

The bridge crane continues to raise the conduit section until it clears the main deck and is snub in a bridge crane pipe guide means indicated by reference numeral 810. The bridge crane then travels forwardly from the dotted line position as seen in FIG. 18, to the full line position as seen in this figure until it is over the movable support means or platform dolly 462. The conduit section is then lowered until the lower flange thereof is bolted to a mating flange on a conduit section supported by dolly 462. The bridge crane holds and guides the conduit section until it clears the guide 810, whereupon the bridge crane is adapted to move aft into the phantom line position whereupon it is adapted to handle another conduit section.

It will be understood that the stowage procedure in connection with operation of the bridge crane is just the reverse of the removal procedure as set forth above.

Movable support means

Referring particularly now to FIGS. 18 through 23 inclusive, the movable support means includes a body means of rigid heavy-duty construction, this body means comprising a plurality of frame members which may be of I-beam cross sectional configuration, these various frame members being rigidly interconnected with one another as by welding or the like. As seen most clearly in FIG. 19, the framework of the body means is made up of a pair of forward frame members 812 and 813, and a pair of frame members 814 and 815 being connected respectively with one end of the frame members 812 and 813, and converging toward one another and interconnected with one another at the opposite end thereof. Frame members 814 and 815 define a substantially V-shaped cutout portion as indicated by reference numeral 817 at the forward part of the movable support means, this V-shaped cut out portion being adapted to receive a part of the truss means as will hereinafter appear while lifting and lowering the truss means into and out of operative mining position. As seen in FIG. 19, a removable plate member 818 is disposed at the apex portion of the V-shaped cutout in the body means and may be removed when desired.

A first pair of frame members 820 and 821 extend along the port side of the support means, and a similar pair of frame members 822 and 823 extend along the starboard part of the support means. A rear cross frame member 825 extends between the end portions of the frame members 821 and 823.

A pair of cross frame means are indicated generally by reference numerals 827 and 828 and may comprise a single cross frame member or a plurality of sections as illustrated, cross frame means 827 including three sections 830, 831 and 832 as illustrated, and cross frame means 828 including three sections 834, 835 and 836 as illustrated.

A first pair of longitudinally extending brace frame members 838 and 839 extend between the cross frame means 827 and 828, while a second pair of longitudinally extending cross brace members 829 and 830 extend between the cross frame means 828 and the rear cross frame member 825. This over-all arrangement provides a very substantial and rigid framework, the entire framework being covered by a top plate means indicated generally by reference numeral 842.

Four flanged wheels indicated by reference numerals 844 are disposed at the port side of the support means, and four similar wheels 845 are disposed at the starboard side of the support means. These wheels are all rotatably journaled in a conventional manner for rotation with respect to the support means, these wheels being suitably spaced with respect to the spaced portions of the guide track means on the deck such that the movable support means will always remain in supported guided relationship with respect to the guide track means.

A first plurality of bracket means indicated by reference numerals 847 are provided on the upper surface of the top plate means of the movable support means for interconnection with and supporting certain parts of the truss means when moving the truss means into or out of operative mining position. A second plurality of bracket means indicated by reference numerals 848 are provided on the upper surface of the plate means and are adapted to engage certain portions of other parts of the underwater mining equipment such as the buoyancy capsule and the like. In addition, a plurality of foundation members indicated by reference numerals 850 are provided on the upper surface of the top plate means for supporting a part of the underwater mining equipment as for example the dead weight means.

A central hole 852 is provided through the upper plate means, and it will be noted that the various frame members are offset with respect to this hole such than an opening is provided through the central portion of the body means through which certain parts of the mining equipment may extend. Clamping means is mounted in overlying relationship to this opening through the body means, the clamping means including a pair of clamping members indicated generally by reference numerals 854 and 855. The clamping members include upper engaging portions 856 and 857 respectively which are adapted to engage and support portions of the underwater mining equipment, these engaging portions being illustrated as comprising substantially semicircular portions which in the present invention are adapted to engage the outer portions of an associated conduit section for holding the conduit section in the operative relationship as will hereinafter appear.

As seen in FIG. 19, the uppermost portions of clamping members 854 and 855 terminate at points 856 and 857 to define a gap therebetween while the upwardly facing engaging portions 856 and 857 extend to substantially abutting relationship with one another and define side surfaces 858 and 859 which as seen in this figure taper inwardly toward one another. The space between portions 856 and 857 is adapted to receive the electrical power and television cables associated with the underwater equipment as well as the air pipe extending upwardly from the dead weight means as described hereinbefore. The sloping surfaces 858 and 859 will serve to cam the flexible cables outwardly as the clamping portions are moved together and ensure that the cables will not be pinched between the clamping portions as they come together.

Guide means is provided for guiding the movement of said clamping members toward and away from one another, the guide means including first pairs of rollers 860 and 861 at one side of the clamping members 854 and 855 respectively, and second pairs of rollers 862 and 863 provided at the opposite side of the clamping members 854 and 855 respectively. A first pair of guide rails 865 and 866 supported on plate 842 are provided for operatively cooperating with the guide rollers 860 and 862 of clamping member 854 to guide the movement of this clamping member with respect to the body means. A second pair of guide rails 868 and 869 are provided for cooperating with the rollers 861 and 863 of the clamping member 855 to guide the movement of the clamping member with respect to the body means.

Referring now particularly to FIG. 23, a means for locking the rollers of the clamping members in operative position is illustrated, it being understood that one of these locking mechanisms is associated with each of the roller means, the particular locking mechanism illustrated being associated with the rollers 863.

As seen in FIG. 23, a cutout portion 870 is provided in the upper plate means 842 and a support portion 872 is disposed within this cutout portion and has a clearance therewith for movement in an upward and a downward direction. Support portion 872 also includes an upwardly

extending guide rail 873 which is aligned with the guide rail 869 supported on the upper plate means 842.

A bracket means 875 is disposed in depending relationship from the adjacent frame member 835, this bracket member including wall portions 977 within which is seated a compression spring 878. It is apparent that the spring 878 will normally hold the support portion 872 in its position as shown in FIG. 23 wherein the upper surface thereof is substantially flush with the upper surface of the adjacent plate means 842. The spring means such as 878 of the various locking mechanisms is of sufficient strength to maintain the associated support portions such as 872 in their up position as shown when the rollers are supported thereon, and accordingly, the springs will normally support the weight of the clamping members. On the other hand, when the clamping members are under load when supporting a part of the underwater mining equipment, the support portion 872 will be moved downwardly into the dotted line position. It is apparent that when the support portion has been so moved downwardly, the associated supported roller means 863 will be prevented from rolling back toward the inoperative position and will accordingly be maintained in its forward clamping position until the load is removed from the clamping members, whereupon the spring means will again urge the support portion 872 upwardly to its original upward position and the clamping members can be withdrawn.

Additional guide means for the clamping members as seen most clearly in FIG. 21 include a pair of guide rods 880 and 881 operatively connected with clamping members 854 and 855 respectively. These guide rod means are slidably supported within cooperating holes provided in the longitudinally extending frame members 838 and 839 respectively, the intercooperation between these guide rod means and such frame members serving to additionally guide the clamping members in their movement into and out of clamping position.

Power operated means in the form of hydraulic ram means includes a lower hydraulic cylinder 883, the piston of which is connected with clamping member 854 by means of a connecting rod 884. An upper hydraulic cylinder 885 includes a piston which is connected with clamping member 854 by a connecting rod 886. Similar hydraulically operated means is operatively connected with clamping member 855 and includes a lower hydraulic cylinder 890, the piston of which is connected by means of connecting rod 891 with clamping member 855. An upper hydraulic cylinder 893 includes a piston which is connected with the clamping member 855 by a connecting rod 894. It will be noted that the lower hydraulic cylinders 883 and 890 are much larger than the upper hydraulic cylinders 885 and 893. The upper hydraulic cylinders 885 and 893 are fast acting cylinders adapted to move the clamping members through a substantial distance of travel rather quickly, while the lower cylinders 883 and 890 are slow acting cylinders adapted to apply clamping pressure to hold a supported underwater mining equipment component in operative clamped position between the clamping members.

It is apparent that the power operated hydraulic ram means are adapted to move the clamping members into and out of operative clamping relationship with respect to one another, any suitable control means being provided for controlling the operation of these hydraulic rams.

As seen particularly in FIG. 19, an electric motor 896 is supported by the body means and is operatively connected with a hydraulic pump 897 which in turn is connected in the usual manner with the sump tank 898. The pump 897 is operatively connected by suitable conduit means with each of the hydraulic ram means, the aforementioned control means being connected in such conduit means for controlling the operation of the ram means. The hydraulic pump 897 is also connected with a conventional hydraulic motor 900.

Hydraulic motor 900 is supported beneath the top plate means of the body means and is connected by a drive shaft means 902 with a speed reducer means 903. A conventional brake mechanism is indicated at 904 and may be controlled by hand for applying the brake when desired.

The output of the speed reducer means 903 is connected with a driving shaft 905 the opposite end of which is rotatably supported in a bearing means 906 supported by a downwardly extending bracket 908. A pair of drive sprockets 910 and 911 are connected with space portions of the drive shaft 905.

A longitudinally extending frame support member 913 is supported between cross frame means 828 and rear cross frame member 825 and supports a pair of spaced bearings 914 and 915. A drive shaft 917 is supported between bearing 915 and a bearing 918 supported at the port side of the movable support means, and a similar drive shaft 920 is supported between bearing 914 and a bearing 921 provided at the starboard side of the movable support means.

Sprockets 910 and 911 are operatively connected respectively with the drive shafts 920 and 917. A first chain driving connection 923 is provided between sprocket 910 and a sprocket 924 fixed to shaft 920, and a second driving chain connection 925 is provided between sprocket 911 and a sprocket 926 fixed to shaft 917. In this manner, drive is transmitted from the drive shaft 905 to each of the drive shaft 917 and 920 which have respectively the sprockets 927 and 928 operatively secured to the outer ends thereof.

The sprockets 927 and 928 at opposite sides of the movable support means are adapted to cooperate with means such as lengths of roller chain indicated by reference numerals 930 and 931 which can be suitably secured as by welding to the upper surface of the deck means. The intercooperation between the fixed roller chain means and the rotating sprockets 927 and 928 serve to provide a means for positively driving the movable support means fore and aft of the ship.

The guide track means 458 and 460 previously described are provided at the port and starboard sides respectively of the movable support means and serve to support and guide the wheels of the movable support means in the movement of the movable support means fore and aft of the ship.

Wedge locking means is provided for selectively locking the movable support means in a particular position relative to the deck. A first pair of spaced wedge bearing portions 934 and 935 are provided at the port side of the body means and a second pair of spaced wedge bearing portions 937 and 938 are provided at the starboard side of the body means. Each of these wedge bearing portions has a substantially channel-shaped cross sectional configuration as seen in FIG. 20 and further as seen FIG. 21, the downwardly facing surface of the central portion of each of these channel-shaped bearing portions slopes downwardly from the outer side of the movable support means toward the inner portion of the movable support means.

The wedge locking means also includes a plurality of wedge members 940 each of which has been given the same reference numerals since these wedge members are of identical construction. The wedge members each include an upwardly facing surface 941 which slopes downwardly and inwardly toward the inner portion of the associated movable support means so as to fit snugly against the aforementioned downwardly facing surface of the wedge bearing portions. These wedge members are each connected with an enlarged body portion 943 which in turn is supported for movement along the deck by means of four roller members 944 rotatably supported at spaced side portions of this wedge portion. The rollers are adapted to roll along inclined portions 945 supported by the deck.

A pair of spaced upwardly extending guide members 946 are provided on the deck in association with each of the wedge members and is adapted to engage opposite sides of the wedge members for guiding them in their movement into and out of wedging locking relationship with the wedge bearing portions on the body means.

As seen particularly in FIG. 19, a first pair of upstanding lugs 947 are supported on the deck and serve to pivotally support a wedge locking lever 948 on a pin means 949 extending between the lugs. A second pair of upwardly extending lugs 950 are supported by the deck and are adapted to receive the opposite end of the locking lever therebetween, the lugs 950 and the locking lever being provided with openings which are adapted to be aligned with one another so as to receive a locking pin 951 therethrough for holding the locking lever in its locking position.

The locking lever is provided with a portion 952 thereon which is adapted to cooperate with a portion 953 on the part 943 of the wedge member, these two interengaging portions 952 and 953 being provided with complementary surfaces. When the locking lever is in the position shown in full line in FIG. 19, the wedge members are at their inner limit of movement in engagement with the wedge bearing portions on the body means, and outward movement of the wedge members is positively prevented. On the other hand, the wedge locking levers may be swung into the phantom line position as shown in FIG. 19 whereupon each of the associated wedge members may be withdrawn outwardly away from the wedge bearing portions on the body means.

The wedge members may be moved into the operative locking position by any suitable means. As seen particularly in FIG. 21, wedge bearing plates 955 are disposed beneath the wedge members when the wedge members are moved inwardly thereby supporting such wedge members. The intercooperation between the sloping surfaces formed on the wedge bearing portions of the body means and the upper surfaces of the wedge members serves to lift the body means upwardly to lift the wheels of the body means off of the associated track and to also raise the driving sprockets 927 and 928 out of interengagement with the drive portions 930 and 931 secured to the deck. It is accordingly apparent that when the wedge members are in this position, the movable support means will be positively prevented from moving along the deck.

As seen in FIG. 21, each of the wheels 844 and 845 disposed at the port and starboard side respectively of the body means is provided with a vertical flange which normally cooperates with the guide track means to properly guide movement of the movable support means. The wedge bearing plates 955 are each provided with a cutout portion 957 which is adapted to receive this vertical flange portion of the associated wheels so as to permit the wheels to freely pass over the upper surface of the wedge bearing plate portions, the upper surfaces of which are flush with the adjacent guide track portions.

Referring again to FIG. 19, it will be noted that a pair of removable plate portions 959 and 960 are provided, these removable platen portions being supported on the upper portion of the frame means and permitting operating personnel to gain access to the clamping members and any equipment which may be supported thereby. These removable plate members may be taken away when it is desired or necessary to have a full clearance of the opening provided in the body means.

Also as seen in FIG. 19, the movable support means is provided with laterally extending towing pins 961 extending outwardly from the central web of frame members 820 and 822 at opposite sides of the movable support means. These towing pins may be utilized for towing a pumping dolly means along the deck.

Auxiliary support means

Referring now particularly to FIGS. 24 through 27 in-

clusive, the auxiliary support means of the present invention comprises a pair of movable portions indicated generally by reference numerals 1014 and 1015. Each of these movable portions comprises an open framework type construction formed of heavy tubular members for maximum strength and rigidity, the movable portion 1014 including a pair of members 1017 and 1018 which converge toward one another and which are secured at the upper ends thereof to a support portion 1020. A cross member 1022 is fixed at its opposite ends to an intermediate portion of members 1017 and 1018 to provide a reinforced A-frame construction.

The movable portion 1015 in a like manner includes a pair of members 1024 and 1025 which are secured at the upper ends thereof to a support portion 1026, a cross member 1027 being secured to intermediate portions of members 1024 and 1025 for reinforcing the structure and to provide an A-frame construction. All of the various members of the two movable portions may be suitably 20 fixedly secured to one another as by welding and the like.

Referring now particularly to FIG. 26, which is a view looking up into the well portion from the bottom of the ship means, it will be noted that the substantially rectangular shaped well portion indicated by reference numeral 125 includes a plurality of walls which define a central well area through which the various underwater components pass during lowering of the equipment into mining position and raising of the equipment from mining position. An aft wall portion 1030 defines the aft part 30 of the well area, and is formed so as to define the cutout portion 1031, it being noted that the side wall portion 1032 and 1033 taper downwardly and outwardly from the top portions 1032' and 1033' respectively thereof to the lower portions 1032" and 1033" respectively thereof, outwardly extending portions 1035 and 1036 being provided for supporting in combination with the lower parts of said side wall portions the tubular parts 1039 and 1040. These tubular parts are mounted for pivotal movement by means of suitable bearing means indicated at 1041 and 1042, 40 these tubular portions being connected to the lower ends of members 1017 and 1017 of the movable portion 1014.

At the opposite side of the well portion as seen in FIG. 26, wall portions 1045, 1046, 1047, 1048 and 1049 define the forward extent of the well area, the wall portions 45 1045 and 1049 being recessed as indicated at 1052 and 1053 respectively to provide clearance for the members 1024 and 1025 of the movable portion 1015. Outstanding portions 1055 and 1056 serve to cooperate with wall portions 1045 and 1049 respectively to rotatably support tubular portions 1058 and 1059 on bearing means indicated at 1060 and 1061. These tubular portions 1058 and 1059 are secured respectively to the lower ends of the members 1024 and 1025 of the movable portion 1015 whereby this movable portion is pivotally supported 55 for movement with respect to the well portion.

The wall portions 1062, 1063, 1064, 1065, 1066, 1067, 1068 and 1069 cooperate with the elevator guide portion 1070 to define the starboard extent of the well area, and the wall portions 1072, 1073, 1074, 1075, 1076, 1077, 60 1078 and 1079 cooperate with the elevator guide portion 1080 to define the port extent of the well area.

The movable portions 1014 and 1015 are adapted to be pivoted upwardly into the recess portions provided adjacent the well area so as to provide a substantially unobstructed central well area through which the mining equipment can be lifted and lowered. It will be noted however, that each of the movable portions is normally stowed in a recessed portion of the well area as aforescribed, and accordingly the movable portions can be completely removed from the well area by detaching the bearings from 65 the associated tubular portions to thereby permit complete removal of these movable portions.

Means is provided for pivoting the movable portions 1014 and 1015 into and out of operative supporting position. The support portions 1020 and 1026 are provided

with radially outwardly extending lugs 1082 and 1084 respectively which are secured to one end of cables 1085 and 1086 respectively. These cables are in turn secured on cable drums 1090 and 1091 respectively which are connected with drive shafts 1093 and 1094 therefor which are in turn connected to bevel gears 1095 and 1096 respectively. The driving shafts are in turn adapted to be driven by hand wheels 1098 and 1099 respectively which are connected with vertically extending shafts 1102 and 1103. These shafts are adapted to be removed and are interconnectable with recessed fittings provided in the deck, these recessed fittings in turn being connected with bevel gears 1104 and 1105 which mesh with the gears 1095 and 1096 respectively.

It is apparent that by inserting the hand wheels and associated shafts into the fittings and turning the hand wheels, the movable portions 1014 and 1015 may be pivoted into the recessed areas provided adjacent the well or they can be pivoted inwardly or lowered into the operated supporting position as illustrated in full lines in the drawings. The movable portions are illustrated in their retracted or inoperative position in phantom lines in FIGS. 24, 25 and 27.

As seen particularly in FIGS. 24 and 25, the support portions 1020 and 1026 are respectively provided with recessed or cutout areas 1107 and 1108 which define upwardly facing surfaces 1107' and 1108' which actually engage and support certain portions of the underwater mining equipment such as the flanges or collars provided on the individual conduit sections. Each of these cutout portions or recesses is substantially arcuate in configuration so as to substantially conform to the shape of the flanges or collars on the conduit sections. A conduit section is illustrated in phantom lines in FIGS. 24 and 25 in a typical supported position with respect to the movable portions of the support means.

Locking means is provided in the form of a pair of arms 1110 and 1111 as seen particularly in FIG. 26 for example, these arms each being pivotally supported as indicated at 1112 and 1113 on the support portion 1020 and being movable into contacting relationship with the support portion 1026 and secured in operative position by suitable lock pins indicated by reference characters 1115. When the locking means is in this locked position, it serves to prevent the support portions from separating from one another thereby holding the support portions in the operative supporting position at the central part of the well. When it is desired to release these locking members, the pins 1115 are removed and the arms are swung away from the support means 1026 thereby permitting free pivotal movement of the movable portions 1014 and 1015.

Supported within the well portion below the auxiliary support means described above is a snubber means indicated generally by reference numeral 1120. This snubber means includes a collar means comprising a pair of substantially semicylindrical portions 1121 and 1122 which have radially outwardly extending flanges 1123 and 1124 respectively formed at opposite ends thereof. These flanges are adapted to be placed in abutting relationship with one another and detachably secured together by suitable nut and bolt assemblies in a conventional manner.

The portion 1122 of the collar means is provided with a pair of spaced outwardly extending lugs 1126 and 1127 and a portion 1121 of the collar means is provided with a similar pair of spaced outwardly extending lugs 1128 and 1129.

A first cable means 1131 is connected between lug 1126 and a lug 1132 secured to the fixed wall 1064 previously described as seen in FIG. 26. A cable 1134 is connected between the lug 1128 and a lug 1138 secured to the fixed wall 1047 previously described. A cable 1137 is connected between the lug 1128 and a lug 1138 secured to the fixed wall 1030 previously described, and a cable 1140 is connected between the lug 1129 and a lug 1141 secured to the fixed wall 1077 previously described. It will be noted

that turnbuckles 1143, 1144, 1145 and 1146 are connected between cables 1131, 1134, 1137 and 1140 and the associated lugs 1132, 1135, 1138 and 1141 so that by adjustment of these turnbuckles the slack may be removed from the cables so as to hold the collar means of the snubber means in fixed position at the central part of the well. It will also be noted that the lugs 1126, 1127, 1128 and 1129 are disposed at substantially 90° angles with respect to one another such that when the over-all arrangement of the snubber means is in its operative position, the cables 1131 and 1140 are aligned with one another and disposed at 90° angles to the cables 1134 and 1137 which are also aligned with one another.

It will be noted that the snubber means is particularly adapted for use for engaging the lower part of the conduit section when such conduit section is supported by the auxiliary support means previously described, this overall arrangement being shown in FIGS. 24 and 25. The two portions of the collar means are adapted to be snugly clamped about the outer surface of the conduit section and to hold this part of the conduit section from movement relative to the walls of the well portion. The particular manner of use of the auxiliary support means as well as the snubber means will be described in detail hereinafter.

Elevator operating mechanism

Referring now particularly to FIGS. 28 through 33 inclusive, the means for lifting and lowering the elevator means 128 may be most clearly understood. The elevator means as seen in FIGS. 28, 29 and 30 is illustrated in its topmost operative position. As seen in these figures, four fixed sheave members 1150, 1151, 1152 and 1153 are supported at the port side of the ship by the superstructure previously described. Four similar fixed sheave members, 1155, 1156, 1157 and 1158 are supported at the starboard side of the ship by the superstructure. Any suitable mounting and support means may be employed for supporting these sheave members in the proper operative position, an open type truss framework being provided for this purpose as seen in these figures.

The drive mechanism for the lifting and lowering means includes an electric motor 1160 which drives a hydraulic pump 1161, the motor and pump being supported on the deck means 1162. The hydraulic pump is in turn operatively connected by suitable conduit means with a hydraulic motor 1165. This hydraulic motor is operatively connected with speed reducer mechanism 1166 which also has a hydraulic brake mechanism 1167 associated therewith for stopping the drive mechanism when desired. The output of the speed reducer mechanism is connected with drive shafts 1170 and 1171 which in turn are operatively connected with gear boxes 1173 and 1174.

A first pair of vertically extending ball bearing screw members 1176 and 1177 are rotatably supported by the output of gear box 1173, and a second plurality of vertically extending ball bearing screw members 1178 and 1179 are rotatably operatively supported by the output of gear box 1174. The ball bearing screw members 1176 and 1177 are supported at intermediate points by radial bearings 1182 and 1183 respectively, the upper ends of these ball bearing screw members being supported by thrust bearings 1184 and 1185 respectively. In a similar manner, the intermediate points of ball bearing screw members 1178 and 1179 are supported by radial bearings 1187 and 1188 while the upper ends of these last-mentioned ball bearing screw members are supported within the thrust bearings 1190 and 1191. The radial bearing means in each case may also include in association therewith a ball bearing spline means, the ball bearing screw and ball bearing spline means being of conventional construction and interacting with one another in the usual manner.

A first pair of sheave members 1193 and 1194 is operatively associated with ball bearing screw member 1176, similar pairs of sheave members 1195 and 1196, 1197 and 1198 and 1200 and 1201 being operatively associated with

the ball bearing screw members 1177, 1178 and 1179 respectively. In each case, the upper sheave member of the pairs of sheave members is smaller than the lower sheave member, and a typical construction is shown in FIG. 33 wherein it will be seen that the ball bearing screw members 1176 and 1177 extend downwardly through central portions 1203 and 1204 of the sheave members 1193 and 1195 respectively to provide a threaded interconnection therewith. Each of the various sheave members is so interconnected with its ball bearing screw member such that upon rotation of the ball bearing screw members in one direction, the pair of sheave members associated therewith move away from one another, while rotation of the ball bearing screw members in the opposite direction causes the pair of associated sheave members to move toward one another.

A first cable means indicated generally by reference numeral 1207 is connected with one corner portion of the elevator means as seen in FIG. 28 for example, this cable means being reeved over fixed sheave members 1150 and 1153 and thence downwardly within the protecting trunk portion 437, the cable means passing around the bottom movable sheave 1194 and thence upwardly over the movable sheave 1193, the cable means then being reeved around these sheave means and finally dead ended or fixedly secured to a dead end foundation beam 1208.

A second cable means indicated generally by reference numeral 1210 is connected with a second corner portion of the elevator means and is reeved over fixed sheave members 1151 and 1152 and thence downwardly within the protecting trunk portion 437, the cable means passing around the bottom movable sheave 1196 and thence upwardly over the movable sheave 1195, the cable means then being reeved around these sheave means and finally dead ended or fixedly secured to the dead end foundation beam 1208.

A third cable means indicated generally by reference numeral 1212 is connected to still a third corner portion of the elevator means and is reeved over fixed sheave members 1155 and 1158 and thence downwardly within the protecting trunk portion 438, the cable means passing around the bottom movable sheave 1201 and thence upwardly over the movable sheave 1200, the cable means then being reeved around these sheave means and finally dead ended or fixedly secured to a dead end foundation beam 1214.

A fourth cable means indicated generally by reference numeral 1216 is fixed to the fourth corner portion of the elevator means and is reeved over fixed sheave members 1156 and 1157 and thence downwardly within the protecting trunk portion 438, the cable means passing around the bottom movable sheave 1198 and thence upwardly over the movable sheave 1197, the cable means then being reeved around these sheave means and finally dead ended or fixedly secured to the dead end foundation beam 1214.

Means is provided for guiding the vertical movement of the movable sheave means, this means taking the form of a plurality of guide rails. As seen particularly in FIG. 33, the movable sheave means 1193 is provided with similar outstanding lug portion 1220 at the opposite sides thereof, a pair of such lug portions being provided on each side of the sheave means and defining a space therebetween. These lug portions receive within the space defined therebetween guide rail means indicated by reference numeral 1222 which may be of substantially T-shaped cross sectional configuration as illustrated.

It will be understood that each of the various movable sheave means is provided with similar lug portions 1220 and similar guide rails 1222 are provided for guiding the vertical movement of the sheave members. Accordingly, all of the various lug means and the various guide rails have been given the same reference numerals since they are of identical configuration and serve the same purpose.

Referring now particularly to FIG. 29, the elevator machinery room is indicated generally by reference num-

eral 1225, it being noted that the hydraulic motor 1165 and the speed reducer 1166 are supported by a deck means 1227. A motor controller mechanism 1228 is illustrated as being supported within the space 1230 of the machinery room between the deck means 1162 and the deck means 1232. The motor controller mechanism is of conventional construction and operatively connected with the motor 1161 previously described for controlling the operation thereof. Ladders 1234 and 1235 are indicated as depending from the hatch portions 1236 and 1237 of the deck means 1162 and 1232 respectively.

The pumping means of the underwater mining equipment as previously referred to employs a separate motor and a separate pump mechanism therein. A spare motor 15 for use in this pumping means is illustrated at 1240 and supported on foundations 1241 which in turn rest upon the deck 1242. A spare pump for use in this pumping means is illustrated by the reference numeral 1245 and is supported upon foundation portions 1246 which in 20 turn rest on deck 1242. A ladder 1247 depends from hatch 1248 provided in deck 1242.

Referring now to FIG. 30, a pair of girders 1250 are illustrated as being secured to the side of the well portion, a similar pair of girder members being secured to 25 the opposite side of the well portion. These girder members extend inwardly toward the central portion of the well, and serve as limit stop means for limiting the downward movement of the elevator means within the well portion.

30 A first pair of inwardly extending lock members 1252 are secured to the bulkhead defining the side of the well portion, and a second pair of spaced lock members 1253 similar to the first pair also extend inwardly from such bulkhead. Aligned holes 1254 and 1255 are formed 35 through the lock members 1252 and 1253 respectively. Similar lock members are disposed in opposing relationship at the opposite side of the well portion to those shown. The aligned openings in the various lock members are adapted to receive lock pins which extend through 40 suitable openings provided in portions of the elevator means adapted to fit between these lock members so as to positively lock the elevator at the level of said lock members. When the elevator is locked in operative position as indicated by phantom line 1257, the elevator is 45 mounted in position for supporting underwater mining equipment therefrom by gimbal means as hereinafter described while the underwater mining equipment is in operation.

Spaced above the lock members previously described 50 are a first pair of similar lock members 1262 and a second pair of similar lock members 1263, opposing similar lock members being provided at the opposite side of the well portion at the same level. These last-mentioned lock members 1262 and 1263 are adapted to cooperate with 55 the elevator means in the same manner as aforesaid so as to lock the elevator means in its normal stowed position as illustrated by phantom line 1265 when not conducting underwater mining operations.

A further pair of lock members 1266 are supported by 60 the superstructure, and a similar pair of lock members 1267 are also supported by the superstructure. It will be understood that similar opposed pairs of lock members are supported from the superstructure at the opposite side of the well portion. These last-mentioned lock members 1266 and 1267 are adapted to cooperate with the 65 elevator means so as to lock the elevator means in the position shown in full lines in FIG. 30 high above the deck, this position comprising a pumping means repair position for the elevator means as hereinafter described.

Elevator construction

Referring now particularly to FIGS. 34, 35, 36 and 37, the details of construction of the elevator means itself will be clearly understood. As seen particularly in FIG. 34, the body means of the elevator means comprises a

substantially open framework composed of a plurality of members of I-beam cross sectional configuration which are rigidly interconnected with one another as by welding or the like. The framework includes a pair of elongated frame members 1270 and 1271 which extend athwartships and which are interconnected by fore and aft extending frame members 1272 and 1273. The outer ends of the frame members 1270 and 1271 define the four corners of the elevator means referred to hereinbefore, the connection of the cable means 1207, 1210, 1212 and 1216 to these four corner portions being indicated in FIG. 34.

The framework also includes a pair of frame members 1275 and 1276 which extend athwartships and which have the opposite ends thereof connected to the frame members 1272 and 1273 respectively. Grating portions 1278, 1279, 1280, 1281, 1282 and 1283 are supported in their positions shown between the frame members for supporting personnel thereon to enable the components of the elevator means or underwater mining equipment supported thereby to be serviced. An electric motor 1285 is supported by the body means and is drivingly interconnected with a hydraulic pump means 1286 also supported by the body means. A drain sump tank 1287 is suitably interconnected by conduit means with the hydraulic pump means and the hydraulic ram means hereinafter described which is operated by the pump means through suitable conventional control means.

The guide means for guiding vertical movement of the elevator means includes the vertically extending guide portions 1070 and 1080 fixedly supported by the ship adjacent the well portion as previously described, these guide portions being disposed in opposing relationship. The roller means on the elevator which cooperates with the guide portions for guiding vertical movement of the elevator may be seen most clearly in FIGS. 34 and 35, these roller means being mounted at opposite sides of the elevator and the roller construction being substantially identical. Accordingly, the roller support arrangement has been given the same reference numerals at opposite sides of the elevator since the construction is identical and further since these roller mechanisms operate in the same manner.

A first pair of laterally extending plates 1290 are secured to the upper portion of the associated frame members 1272 and 1273 respectively at opposite sides of the elevator and a second pair of spaced lower plates 1291 extend from the lower portions of the associated frame members. A pair of vertically extending plates 1293 and 1294 are fixedly secured to the outer portions of the plates 1290 and 1291 previously described.

A pair of horizontally extending plates 1296 and 1297 extend outwardly from the associated frame member to which they are fixed, and horizontally extending bar-like members 1298 and 1299 are secured to the outer ends of plates 1296 and 1297 respectively, the bar members extending between and being secured to the vertically extending members 1293 and 1294.

A first support plate 1302 is secured to members 1293, 1294 and 1298 by any suitable means such as welding or bolts and the like. A second support plate 1303 is secured to members 1298 and 1299 by suitable means such as welding or bolts and the like. A third support plate 1305 is secured to members 1293, 1294 and 1299 by any suitable means such as welding or bolts and the like. These three support plates are provided with openings therein which are adapted to receive and support journal portions 1307, 1308 and 1309 respectively.

The upper and lower journal portions 1307 and 1309 have outwardly extending arm portions 1310 upon which are rotatably supported rollers 1312 of substantially similar construction. These rollers are adapted to engage the bottom surface 1313 of the channel shaped elevator guide portions 1070 and 1080.

The journal portions 1308 supported by plates 1303 include outwardly extending shaft portions 1315 upon which are supported rollers 1316. Rollers 1316 are accordingly rotatably journaled by the journal portions 1308 and engage the side wall portions 1318 and 1319 of the channel shaped elevator guide portions 1070 and 1080, it being apparent that the diameter of rollers 1316 is slightly smaller than the distance between the side wall portions 1318 and 1319 so that the rollers may roll against only one wall portion 1318 or 1319 at any one time.

It is apparent that the rollers 1316 are mounted for rotation about axes which are substantially perpendicular to the adjacent rollers 1312, and it is evident that the rollers will interact with the vertically extending elevator guide portions 1070 and 1080 to assure that the elevator means moves upwardly and downwardly in the proper manner.

As seen particularly in FIGS. 35 and 36, gimbal support means comprises a first pair of plates 1321 and 1322 which extend inwardly from the frame member 1276, a cross plate 1324 being secured between the plates 1321 and 1322 to provide a rigid structure. Attaching plates 1326 and 1327 are secured to the upper surfaces of plates 1321 and 1322, the attaching plates having spaced threaded openings therein for receiving cap screws and the like for attaching the gimbal means hereinafter described to these attaching plates. Small gusset plates 1330 and 1331 are provided beneath the attaching plates to additionally support these plates in operative position.

Catwalk means are indicated generally by reference numerals 1334 and 1335 in FIG. 34 and are disposed on opposite sides of the gimbal support means at the left portion of the elevator means as seen in this figure, and similar catwalk portions 1336 and 1337 are provided at opposite sides of the gimbal support means at the right portion of the elevator means. These catwalk portions each include substantially horizontally extending plate members which are indicated by reference numerals 1340 and 1341 in FIG. 35 upon which personnel are adapted to be supported when servicing the equipment, these plate members extending outwardly from the associated frame members 1275 and 1276 and being additionally supported by similar reinforcing plate members 1343, 1344, and 1345.

It will be understood that the gimbal support structure has been specifically described as supported from frame member 1276. The gimbal support structure supported by frame member 1275 is of identical construction and has been given the same reference numerals primed.

The clamping means on the elevator means includes a pair of clamping portions indicated generally by reference numerals 1350 and 1351, these clamping portions being movably supported with respect to the elevator means and being movable over the central opening defined between the frame members 1275 and 1276 of the elevator framework.

The two movable clamping portions are of substantially identical construction, and accordingly, description of one of these movable portions will suffice, similar portions being given the same reference numeral primed in the other clamping portion. As seen particularly in FIGS. 35, 36 and 37 the clamping portion 1350 includes a support portion 1353 at the upper part thereon which comprises a flat horizontal member having an arcuate inner surface 1355 and a substantially L-shaped cross sectional configuration as seen in FIG. 35 such that a substantially arcuate recess portion 1356 defining an upwardly facing surface 1357 upon which various components of underwater mining equipment is adapted to rest and be supported. It should be noted that support portions 1353 and 1353' terminate at points indicated by reference numerals 1358 to define a space indicated at 1359 in FIG. 34 when the clamping portions 1350 and 1351 are in clamping position as indicated in phantom line, this

space being adapted to receive the aligning lug 605 on a supported conduit section as aforescribed.

As seen particularly in FIG. 34, clamping members 1350 and 1351 terminate at the points 1363 and 1364 respectively which are adapted to define therebetween when the clamping members are in operative clamping position a space for receiving the electrical power and television cables as well as the aforescribed air pipe. These clamping portions also include the portions 1368 and 1369 respectively which extend toward one another and are adapted to be disposed in substantially abutting relationship when the clamping members are in operative clamped position. These latter portions 1368 and 1369 define sloping side surfaces as seen in FIG. 34 so as to create a camming action when the two clamping portions are moved toward one another so as to avoid pinching the electrical power and television cables therebetween. Fixedly secured in depending relationship to the inner portion of member 1353 is a member 1360 having a substantially arcuate cross sectional configuration complementary to the arcuate inner surface 1355 of the member 1353. The arcuate cross section of member 1360 is adapted to fit snugly against the outer surface of an underwater mining component such as a conduit section to hold the conduit section in operative position with an upper flange thereon seated within the recess portion 1356 of member 1353.

Members 1362 and 1362' are of substantially T-shaped cross sectional configuration and members 1365 and 1365' as seen for example in FIG. 37 extend between points indicated by numerals 1366 as shown in FIG. 36 and form the support of clamping portions 1350 and 1351. Reinforcing gusset members 1370 and 1371 are connected between members 1362 and 1365. Gusset members 1373 and 1374 are connected between members 1362 and 1365 and 1375 and 1376 respectively. Gusset members 1390 and 1391 are connected between members 1362, 1365 and 1365. Gusset members 1393 and 1394 are connected between members 1362 and 1365. Gusset member y is connected between members 1362, 1365 and 1360. Gusset member z is connected between members 1360 and 1365.

The above-mentioned elongated plates 1375 and 1376 include depending plate portions 1375' and 1376' secured to the undersurfaces thereof between which are rotatably mounted wheel members 1380 and 1381 as seen in FIG. 36. These wheel members are adapted to roll along guide rails 1385 and 1386 secured to the upper surface of frame members 1275 and 1276 of the elevator means, the wheel members being provided with pairs of spaced flanges 1382 and 1383 for guiding and retaining the wheels on these guide rails.

A transversely extending 1396 extends rearwardly of member 1362 and is connected with a vertically extending member 1398. Power operated means in the form of hydraulic ram means includes a first lower hydraulic cylinder 1400 the piston of which is connected with a connecting rod 1401 which is connected to member 1398. A second upper hydraulic cylinder 1403 has a piston means which is connected with a connecting rod 1404 which in turn is connected with a rear portion of support member 1353.

It will be noted that hydraulic cylinder 1400 is much larger than hydraulic cylinder 1403. The second mentioned hydraulic cylinder is a fast acting cylinder which is adapted to move the clamping portion through a substantial distance of its travel rather quickly, while the first mentioned hydraulic cylinder is a slow acting cylinder which is adapted to apply clamping pressure to hold a supported underwater mining equipment component in operative clamped position between the clamping portions. Any suitable control means may be provided for controlling the operation of the hydraulic ram means which is operatively connected with the hydraulic pump 1286 previously mentioned.

Referring now particularly to FIGS. 38, 39 and 40, the construction of the gimbal means utilized for supporting the conduit means from the elevator means is specifically illustrated.

As seen in these figures, a pair of gimbal support means are indicated generally by reference numerals 1407 and 1408, gimbal support means 1407 including a pair of substantially semi-cylindrical halves 1410 and 1411, while the gimbal support means 1408 includes a similar pair of halves 1413 and 1414. Members 140 and 1411 are attached to each other by bolts b as shown in FIGS. 38 and 39 extending within suitable openings provided in these members. Member 1411 includes a pair of laterally extending flanges 1417 at opposite sides thereof which have holes 1418 formed therethrough for receiving suitable attaching means for securing the gimbal support means on the gimbal attaching members 1326 and 1327 previously described.

Members 1413 and 1414 are attached to each other by bolts b extending within suitable openings provided in these members. Member 1414 includes a pair of laterally extending flanges 1422 at opposite sides thereof which have holes 1424 formed therethrough for receiving suitable attaching means for securing the gimbal support means on the gimbal attaching members previously described.

Referring to FIG. 34, the gimbal means is illustrated in supported operative position within the elevator means, and it will be noted that bolt assemblies 1426 and 1427 are associated with gimbal support means 1408 for attaching the gimbal support means to the two spaced underlying gimbal support members 1326 and 1327. In a similar manner, the other gimbal support means 1407 is attached to its associated gimbal support members on the elevator means by bolt assemblies 1429 and 1430.

Referring now particularly to FIG. 40, it will be noted that the two members 1410 and 1411 of gimbal means 1407 are of generally L-shaped cross sectional configuration and are adapted to support ball bearing means 1432 therewithin, a retaining plate 1434 being held in position at the ends of these members 1410 and 1411 by means of cap screws 1435.

In a similar manner, the two members 1413 and 1414 of gimbal support means 1408 are also of substantially L-shaped cross sectional configuration and serve to support ball bearing means 1438 which is held in place by the retainer plate 1439 supported on members 1413 and 1414 by cap screws 1440.

The gimbal means includes a first substantially annular portion 1443 which includes upstanding portions 1444 and 1445 from which extend the journal portions 1446 and 1447 respectively which are journaled within ball bearing assemblies 1438 and 1432 of the two gimbal support means. With this arrangement, it is apparent that the annular member 1443 is journaled for rotation about a first pivotal axis indicated by the line x—x.

Annular member 1443 also includes a pair of upstanding portions 1450 and 1451 which are disposed at substantially 90° relation to the portions 1444 and 1445. Each of the portions 1450 and 1451 may include lower and upper halves 1450' and 1450" and 1451' and 1451" respectively which are adapted to be secured to one another by suitable nut and bolt assemblies and the like indicated by reference numerals 1456 and 1457. With this arrangement, ball bearing assemblies similar to those previously described may be mounted with these portions and held in place by end plates 1459 and 1460 which are secured in place by suitable cap screws.

As seen particularly in FIG. 40, an annular member 1462 has a cylindrical conduit portion 1463 extending through the center thereof and rigidly secured thereto. The annular member 1462 has a pair of laterally extending journal portions 1464 and 1465 as seen in FIG. 38 which extend within the ball bearing means mounted in

portions 1450 and 1451 of the first annular member. It is accordingly apparent that the second annular member 1462 is journalled for rotation about a second axis y—y which is substantially normal to the first axis x—x previously described.

Referring again to FIG. 40, the lower portion of conduit portion 1463 is secured to a flange portion 1467 having spaced holes 1468 formed therein corresponding in number to the holes provided in the upper flange of a typical conduit section such as 590 whereby flange portion 1467 can be rigidly secured to an associated conduit section. This arrangement serves to support the conduit means from the gimbal means.

The upper part of conduit portion 1463 is indicated as being rigidly secured to a portion 1470 which in turn may be connected with the flexible conduit portion 129 which transfers the collected solid bodies of material to the separation means 130 previously described.

It is evident from the foregoing description that the gimbal means is selectively removable from the elevator means and when in operative position therewithin is adapted to support the conduit means and the associated underwater mining equipment components. When the conduit means and the associated components are so supported, the conduit means is in effect connected with the elevator means by a universal connection due to the fact that the gimbal means permits rotation about two mutually perpendicular axes. This overall arrangement permits the conduit means to have the necessary movement with respect to the ship as is required during normal mining operations due to relative movements which will unavoidably occur between the underwater mining equipment and the ship thereabove.

It is apparent from the foregoing that there is provided according to the present invention a ship and handling means for underwater mining equipment which is particularly for carrying out mining operations at great depths beneath the surface of the sea. The ship is provided with a central well portion and storage means for storing individual sections of conduit or pipe, suitable handling means being provided for moving the sections of conduit to and from the well portion and for lowering the conduit means through the well portion as well as raising it therethrough. This handling means enables effective assembly and disassembly of the conduit means where the individual conduit sections may be of relatively large dimension and in a typical example a conduit section may have a length of approximately 36 feet with an inner diameter of 19 inches. The handling means of the present invention enables such large heavy-duty pieces of pipe to be effectively handled with a minimum number of personnel and further enables assembly and disassembly of the conduit means in a minimum period of time.

As this invention may be embodied in several forms without departing from the spirit or essential characteristics thereof, the present embodiment is therefore illustrative and not restrictive, and since the scope of the invention is defined by the appended claims, all changes that fall within the metes and bounds of the claims or that form their functional as well as conjointly cooperative equivalents are therefore intended to be embraced by those claims.

We claim:

1. Apparatus for underwater mining at great depths beneath the surface of the sea comprising a ship adapted to move through the water, said ship including deck means having track means thereon, movable support means mounted for movement relative to said deck means, said movable support means including body means, means on said body means for supporting said body means for movement along said track means, said body means having an opening formed in a central portion thereof, said opening extending completely through said body means so as to receive portions of under-

water mining equipment extending through said body means, clamping means including a pair of opposed clamping members mounted for movement along the upper portion of said body means and being disposed above said body means, said clamping means being movable with respect to said body means toward and away from one another, each of said clamping members including outer engaging portions adapted to engage and support parts of underwater mining equipment, and means on said body means for moving said clamping members toward and away from one another, said clamping members being adapted to move into operative clamping position in overlying relation to said opening.

2. Apparatus as defined in claim 1 wherein said means for moving the clamping members toward and away from one another comprises power operated means.

3. Apparatus as defined in claim 1 including driving means supported by said body means for positively driving said body means along said track means in the desired direction.

4. Apparatus as defined in claim 1 wherein said body means includes a cutout portion at the forward end of the body means for receiving a part of underwater mining equipment.

5. Apparatus as defined in claim 1 wherein each of said clamping members is mounted on rollers supported on said body means whereby said clamping members may be moved relative to said body means, and guide means for guiding the movement of said clamping means.

6. Apparatus as defined in claim 5 wherein said guide means comprises a plurality of guide rails supported by said body means and adapted to engage said rollers, and guide rod means extending through guide openings formed in said body means.

7. Apparatus as defined in claim 5 wherein said body means is supported for movement along said track means by a plurality of spaced wheel means, and positive drive means for driving said body means relative to said deck means, said positive driving means including portions movably supported by said body means and portions fixedly secured to said deck means.

8. Apparatus for underwater mining at great depths beneath the surface of the sea comprising a ship adapted to move through the water, said ship having a well portion formed therein opening upwardly and also opening downwardly into the sea, elevator means supported by said ship, said elevator means including body means, guide means for guiding the movement of said body means in an up and down direction, said guide means including guide portions supported by said ship adjacent said well portion and interengageable guide portions supported by said body means, said body means having an opening formed completely therethrough, clamping means movably supported on said body means, said clamping means including a pair of clamping members mounted for movement with respect to said body means toward and away from one another and into operative clamping position in overlying relation to said opening, each of said clamping portions including a support portion for engaging and supporting a part of underwater mining equipment, and means for lifting and lowering said body means to move said elevator means in an up and down direction out of and into said well portion.

9. Apparatus as defined in claim 8 including guide rail means supported on said body means, each of said clamping portions including means supporting the associated clamping portion for movement relative to said body means and for engaging said guide rail means to guide the movement of said clamping portions, and power operated means supported by said body means for moving said clamping portions into and out of operative clamping position.

10. Apparatus as defined in claim 8 wherein each of said clamping members is supported on wheel members for movement relative to said body means and for move-

ment over said central opening into clamping position, guide rail means on said body means engaging said wheel members for guiding the movement of said clamping members, and power operated means supported on said body means and engaging said clamping members for moving said clamping members into and out of clamping position.

11. Apparatus as defined in claim 8 wherein said guide means for guiding up and down movement of said body means includes a plurality of rollers supported on said body means.

12. Apparatus for underwater mining at great depths beneath the surface of the sea comprising a ship adapted to move through the water, said ship having a well portion formed therein opening upwardly and also opening downwardly into the sea, elevator means supported by said ship, said elevator means including body means having a central opening therethrough, guide means cooperating with said body means for guiding the movement of said body means in an up and down direction, clamping means including a pair of clamping portions movable toward one another into operative clamping position and movable away from one another out of operative clamping position, said clamping portions being disposed over said central opening when in operative clamping position, guide means on said body means for guiding the movement of said clamping portions, means for moving said clamping portions toward and away from one another, and means for moving said body means in an up and down direction to move the body means out of and into said well portion as desired, said lifting and lowering means including a plurality of sheave means, said sheave means being mounted for movement relative to one another, cable means reeved over said sheave means and connected with said body means, means for moving said sheave means with respect to one another for moving said cable means and said body means, and means guiding the movement of said movable sheave means.

13. Apparatus as defined in claim 12 including lock means supported by said ship and interengageable with a portion of said body means for locking said body means in a particular operative position.

14. Apparatus as defined in claim 13 including limit stop means supported by said ship for engaging and limiting the movement of said elevator means in a downward direction within said well portion.

15. Apparatus for underwater mining at great depths beneath the surface of the sea comprising a ship adapted to move through the water, said ship having a well portion formed therein opening upwardly and also opening downwardly into the sea, elevator means supported by said ship, said elevator means including body means, guide means for guiding the movement of said body means in an up and down direction, clamping means movably supported by said body means, means guiding said clamping means for movement in a proper manner, means for moving said clamping means into and out of clamping position, means for moving said body means in an up and down direction to move the body means out of and into said well portion, and gimbal means supported by said body means, said gimbal means including attaching means for securing the gimbal means to a portion of underwater mining equipment.

16. Apparatus as defined in claim 15 wherein said gimbal means includes a first portion supported by said body means for pivotal movement about a first axis relative to said body means, said gimbal means also including a second portion supported by said first gimbal portion for pivotal movement about a second axis disposed substantially perpendicular to said first axis.

17. Apparatus as defined in claim 16 wherein each of said first and second gimbal portions are substantially annular in configuration and include radially outwardly extending bearing portions which are journaled for rotation in the associated parts.

18. Apparatus for underwater mining at great depths beneath the surface of the sea comprising a ship adapted to move through the water, said ship having a well portion formed therein opening upwardly and also opening downwardly into the sea, elevator means supported by said ship, said elevator means including body means comprising a generally open framework having a central opening formed therethrough, fixed guide portions secured to said ship adjacent said well portion and extending in a substantially vertical direction, a plurality of roller members rotatably supported on said body means and engaging said fixed guide portions for guiding the movement of said body means in an up and down direction, clamping means comprising a pair of clamping portions, each of said clamping portions including inner support portions adapted to engage and support part of underwater mining equipment, said clamping portions being adapted to move into operative clamping position over said central opening, said clamping portions being supported on wheel members for movement with respect to said body means, guide rail means supported on said body means and engaging said wheel members for guiding the movement of said clamping portions, power operated means supported on said body means and connected with said clamping portions for moving said clamping portions into and out of operative clamping position, means for lifting and lowering said body means so as to move it in an up and down direction out of and into said well portion as desired, and gimbal means supported at the central portion of said body means, said gimbal means including a first portion supported by said body means for pivotal movement about a first axis relative to said body means, said gimbal means including a second portion supported by said first gimbal portion and adapted to pivot about a second pivotal axis disposed substantially perpendicular to said first pivotal axis, said gimbal means including attaching means for securing the gimbal means to underwater mining equipment.

19. Apparatus as defined in claim 18 wherein said rollers mounted on said body means for guiding the movement thereof comprise at least one roller disposed for rotation about a first axis and at least a second roller disposed for rotation about a second axis disposed substantially normal to said first axis.

20. Apparatus as defined in claim 18 wherein said lifting and lowering means comprises movable sheave means and fixed sheave means, cable means reeved over said movable and fixed sheave means and connected with said body means, means for guiding the movement of said movable sheave means, and means for moving said movable sheave means so as to cause movement of said cable means to lift and lower said body means as desired.

21. Apparatus as defined in claim 18 including fixed locking portions secured to said ship, and cooperating locking means on said elevator means for locking said elevator means in a fixed operative position, and means on said ship for limiting downward movement of said elevator means within said well portion.

22. Apparatus for underwater mining at great depths beneath the surface of the sea comprising a ship adapted to move through the water, said ship including deck means, movable support means mounted for movement relative to said deck means, said movable support means including body means, means supporting said body means for movement along said deck, said body means having an opening formed therethrough for receiving parts of underwater mining equipment, clamping means comprising a pair of opposed clamping members supported on said body means for movement toward and away from one another, said clamping members each having an outer engaging portion adapted to engage and support a part of underwater mining equipment, said clamping means being supported for movement into operative clamping position in overlying relationship to said opening, and power operated means supported on said body

means and operatively connected with said clamping members for moving the clamping members toward and away from one another, said body means being provided with wedge bearing portions, and wedge locking means including a plurality of wedge members mounted for movement relative to said deck, means guiding said wedge members for movement into and out of operating position in engagement with said wedge bearing portions on said body means, and means for holding said wedge locking means in operative locking position.

23. Apparatus as defined in claim 22 wherein said wedge members include sloping upper surfaces adapted to engage complementary sloping downwardly facing surfaces on said wedge bearing surfaces.

24. Apparatus for underwater mining at great depths beneath the surface of the sea comprising a ship adapted to move through the water, said ship including deck means, movable support means mounted for movement relative to said deck means, said movable support means including body means, means supporting said body means for movement along said deck means, means guiding said body means for movement in a particular path along said deck means, said body means having a central opening formed therethrough for receiving parts of underwater mining equipment, clamping means comprising a pair of opposed clamping members having outer engaging portions adapted to engage and support parts of underwater mining equipment, each of said clamping members being mounted on rollers supported on said body means whereby said clamping members may be moved relative to said body means, guide means for guiding the movement of said clamping means, and power operated means supported by said body means and operatively connected with said clamping members for moving said clamping members into and out of clamping relationship, and detent locking mechanism on said body means for engaging said rollers and for automatically locking said rollers against movement when said clamping members are under load.

25. Apparatus as defined in claim 24 wherein said detent locking mechanism comprises a plurality of spaced movable portions, each of said movable portions being spring loaded toward a normal unlocked position, said movable portions being movable into locked position against the force of said spring means when a load is applied to said clamping members.

26. Apparatus for underwater mining at great depths beneath the surface of the sea comprising a ship adapted to move through the water, said ship including deck means, movable support means mounted for movement

relative to said deck means, said movable support means including body means, means supporting said body means for movement along said deck means, means guiding said body means for movement in a particular path along said deck means, said body means having a central opening formed therethrough for receiving parts of underwater mining equipment, clamping means comprising a pair of opposed clamping members having outer engaging portions adapted to engage and support parts of underwater mining equipment, each of said clamping members being mounted on rollers supported on said body means whereby said clamping members may be moved relative to said body means, guide means for guiding the movement of said clamping means, and power operated means supported by said body means and operatively connected with said clamping members for moving said clamping members into and out of clamping relationship, said body means being supported for movement along said deck by a plurality of spaced wheel means, guide track means supported by said deck means and cooperating with said wheel means for guiding the movement of said body means along said deck means, and positive drive means for driving said body means relative to said deck means, said positive driving means including portions movably supported by said body means and portions fixedly secured to said deck means, said body means being provided with a plurality of spaced wedge bearing portions, and a plurality of spaced wedge locking means, each of said wedge locking means including a wedge member mounted for movement into and out of operative engagement with one of said wedge bearing portions, means guiding said wedge members for movement into and out of operative position, and means for holding said wedge members in their locked position holding said body means against movement relative to said deck means.
